UNITED STATES PATENT OFFICE

2,056,752

AUTOMATIC TELEPHONE SYSTEM

John H. Voss, Downers Grove, Ill., assignor to
 Associated Electric Laboratories, Inc., Chicago,
 Ill., a corporation of Delaware

Application December 29, 1933, Serial No. 704,465

27 Claims. (Cl. 179—27)

This invention relates to telephone systems in general, but is concerned more particularly with small systems of the type commonly known as private automatic exchanges.

5 Private automatic exchanges are as a rule privately owned by individuals or corporations and are installed in factories or other establishments for providing local service between a small number of local telephone lines and for establishing 10 connections over trunk lines to the main office of the telephone company's network.

The main object of the invention is to provide an improved private automatic exchange system of the type shown in Patent No. 1,888,337, issued 15 November 22, 1932, to John H. Voss, by simplifying and reducing the cost thereof without sacrificing any of the desirable operating features.

20 The three push-buttons and other auxiliary apparatus mounted in the base of the telephone shown in the aforesaid patent is eliminated and replaced in accordance with the present invention by a single push-button mounted either in a standard telephone itself or on the accompanying bell box.

25 Another feature which greatly reduces the cost of this system over the system shown in the aforesaid patent is that in the old system in its simplest form six conductors were required between the telephones and the exchange equipment while in the present case only two conductors are required.

30 Other features of the invention relate to the improved method of answering incoming trunk calls, of transferring trunk calls from one subscriber to another, and of holding and guarding such trunk lines.

35 Another feature of the invention relates to an improved attendant's cabinet which may be cut into service when desired to intercept all incoming trunk calls.

40 Other features of the invention relate mostly to circuit improvements which will be apparent from the following detail description of the drawings comprising Figs. 1 to 7, inclusive, which 45 show by means of the usual circuit diagrams a sufficient amount of apparatus to enable the invention to be described and understood.

45 Fig. 1 illustrates in its lower left-hand corner a local subscriber's telephone S equipped with a 50 push-button PB by means of which the subscriber thereat can make and receive trunk calls, can transfer trunk calls, and can hold a trunk call while making or receiving local calls. Two line circuits, one for information line #01, and 55 the other for line #08, are shown near the center

of Fig. 1. The wipers and motor magnet of one of the local finders are shown at the right of Fig. 1, together with the multiple connections to the other local and trunk finders and connectors.

5 Fig. 2 shows a group of finder-connector relays for controlling the operation of one of the finder and connector switch links, the wipers of which are shown in Figs. 1 and 3, respectively.

Fig. 3 shows the connector wipers of this finder connector link, a subscriber's line and substation S', and a trunk distributor together with its associated relays.

10 Fig. 4 at the left shows a finder connector distributor and its associated relays and at the right shows a transfer distributor and its associated 15 relays.

Fig. 5 at the left shows the equipment at the attendant's cabinet and at the right the wipers and motor magnet of one of the trunk finders 20 together with its multiple connections to the connector and local and trunk finders.

25 Figs. 6 and 7 show the relays of one of the two-way trunks, the associated finder and wipers being shown in Fig. 5.

Referring now to Fig. 1 in detail, all local subscribers' lines, such as S, are equipped with a standard well-known automatic telephone set comprising a calling device CD, a receiver R, transmitter T, switchhook springs SH, ringers RB, and an induction coil. Non-restricted subscribers entitled to make and receive trunk calls as well as local calls have a push-button such as PB mounted in the base of the telephone or on the associated ringer box. Semi-restricted subscribers entitled to answer trunk calls but not originate trunk calls are similarly provided with a push-button, but such subscribers' lines are connected to battery through a resistance, such as Z, over a conductor, such as 29, to its 30 corresponding bank contact accessible to finder wiper 152.

35 Restricted subscribers are not provided with a push-button and can only make and receive local calls. Each subscriber's line extends to a line 45 circuit comprising a two-step line and a cut-off relay, such as relay 103. The conductors extending from the subscribers' line circuits terminate in the banks of both the local and trunk finders in the connector banks.

40 The finder switches are mechanically similar to the well-known rotary lineswitch having no normal position, while the circuits thereof have been altered in accordance with the present invention.

25

30

35

40

45

50

55

The connector switch shown in Fig. 3 is mechanically similar to the finders, but instead of automatically hunting for a marked potential as the finder does, the connector is directly controlled from normal position by impulses.

The trunk distributor shown in Fig. 4 is mechanically similar to the finders and automatically hunts for an idle trunk line or a particular trunk line in use dependent upon whether 10 the call is an outgoing trunk call or an incoming trunk call.

The finder distributor shown in Fig. 4 is mechanically similar to the finders and pre-selects an idle finder connector link for use.

15 The transfer distributor shown in Fig. 4 is also mechanically similar to the finders and is used when a local subscriber desires to transfer a trunk call to another local subscriber. Relay 450 in the transfer-distributor has an armature 20 451 provided with a weight 452 on its movable end to cause such armature to vibrate when the relay releases the armature. Relay 470 in the transfer distributor has a spring 471 with a weight 472 which causes spring 471 to vibrate 25 for a predetermined period when the relay 470 is first energized.

Referring now to the attendant's equipment shown in Fig. 5, the attendant's telephone circuit is mounted on a base and comprises a calling device CD, a handset HS comprising a transmitter and receiver, monophone springs MS which are closed when the handset HS is removed from the cradle, an induction coil IC, and ringers RB. The information key, the hold key, 30 the transfer key, the turn signal key SK, the two release and trunk answering keys, (only one of which is shown), and two supervisory lamps, such as SL, are mounted on top of the base alongside of the attendant's telephone. The relays 516 and 500 to 540, inclusive, and the buzzer B are mounted inside the base. In case a second trunk answer key is provided then another set of relays, such as relays 500 to 540 are also provided since such relays are individual to a trunk 35 answer key. The buzzer B is used when the attendant answers all incoming trunk calls while the trunk signals are used when any non-restricted local line may answer incoming trunk calls. There are as many common trunk signals 40 45 placed throughout the establishment as required to enable the local subscribers to determine when an incoming trunk call is to be answered.

In Figs. 6 and 7, one of a number of two-way trunk circuits is shown connecting the local private exchange with one of the telephone company's exchanges which may be either manual or automatic. When the trunk circuit, shown in Fig. 7 extends to an automatic exchange, a dotted strap shorting the winding of relay 720 50 is provided, while this strap is cut when the trunk circuit extends to a manual exchange.

Having described the equipment and apparatus, a detailed description of the operation will now be given. Briefly, local calls are completed in the following manner: The local calling party removes his receiver and, after hearing dial tone, dials the number of the desired station. If the called line is not busy, the called station will be rung automatically and intermittently. If the called line is busy, the calling party will receive the busy tone. The release of the local call is under control of the calling party.

In order to describe a local call in detail, it 75 will be assumed that subscriber S desires to call

subscriber S' shown in Fig. 4. Responsive to the removal of the receiver, switchhook spring SH closes a circuit for energizing the combined line and cut-off two-step relay 103 in its first step as follows: from ground by way of armature 108, conductor 102, lower winding of the induction coil, transmitter T, through the impulse springs of the calling device CD, through the upper switchhook springs to conductor 101 and thence by way of armature 104 through 10 the upper resistance winding and through the lower winding of two-step relay 103 to battery. Due to the resistance in the upper winding of relay 103, this relay is energized in its first step to close only armatures 105 and 107. At armature 105 relay 103 marks the line S as calling in the bank of the local finder by connecting the battery through the lower winding of relay 103 to the fifteenth bank contact accessible to finder wiper 153.

At armature 107, relay 103 grounds the finder start conductor 9 to complete a circuit for the start relay 420 in the finder connector distributor shown in Fig. 4 as follows: from ground by way of armature 106 in its normal position, armature 107 in operated position, common finder start conductor 9, through the winding of slow-to-operate start relay 420, armature 422, interrupter springs 404 and through the winding of the distributor motor magnet 405 to battery. 25 Motor magnet 405 is marginal and will not energize in series with the winding of relay 420 or in series with resistance 423. At armature 422 relay 420 removes the obvious short circuit from around resistance 423 for a purpose to be more 30 fully described hereinafter, and at armature 421 completes an obvious circuit for energizing relay 400. At armature 401 relay 400 prepares a point in the circuit for the finder test circuit; at armature 402 and its working contact completes 35 the circuit for energizing slow-to-release relay 410; and at armature 403 completes the circuit for energizing the finder motor magnet 168 as follows: from ground by way of armature 205, armature 231 and resting contact, conductor 45 215, bank contact and wiper 416, armature 403, wiper 415 and engaged bank contact, conductor 167, and through the winding of motor magnet 168 to battery.

Magnet 168, upon energizing, positions its 50 pawl preparatory to stepping the wipers of the local finder and at springs 169 completes the circuit for energizing the combined line, stepping and test relay 230 as follows: from ground by way of springs 169, conductor 166, and 55 through the upper winding of relay 230 to battery. Relay 230, upon energizing, at armature 231 opens the previously traced circuit for motor magnet 168, whereupon motor magnet 168 deenergizes to advance the wipers of the local finder into engagement with their next bank contacts. The deenergization of motor magnet 168 also opens the circuit of relay 230 at springs 169, with the result that relay 230 now deenergizes. The deenergization of relay 230 again completes 60 the previously traced circuit for motor magnet 168 and motor magnet 168 again completes the circuit for energizing relay 230 to cause the latter relay to open the circuit to motor magnet 168 and cause the latter to step the wipers into 65 engagement with their next bank contacts. In the same manner as just described magnet 168 and relay 230 operate until test wiper 153 encounters a calling potential of a calling line.

When test wiper 153 encounters a bank con- 75

tact of a calling line marked with calling potential, the following circuit is completed for maintaining relay 230 energized and for energizing relay 220 and relay 103 in its second step. This 5 circuit may be traced as follows: from ground through the lower winding of relay 230, through the normally closed springs controlled by armature 226, lower winding of relay 220, conductor 228, bank contact and wiper 412, armature 401, 10 wiper 413 and engaged bank contact, conductor 163, test wiper 153 in engagement with the bank contact terminating the test conductor of subscriber S, conductor 111, armature 105, and through the lower winding of relay 103 to battery. Relay 230 is maintained energized over this circuit and relay 220, upon energizing, at 15 armature 221 completes a circuit for energizing slow-to-release relay 210 by way of armature 231 and its working contact; at armature 222 prepares a point in the circuit for energizing relay 280; at armature 223 prepares a point in the circuit for energizing series relay 270; at armature 244 connects ground to the guard lead 227 to make this finder connector link busy; at armature 225 connects ground to conductor 163 to maintain relay 103 in energized position and to busy the calling line in the banks of the finders; and at armature 226 connects the lower winding of relay 230 to the positive talking conductor 30 and at the normally closed springs controlled by armature 226 opens a point in its own circuit through its lower winding.

Slow-to-release relay 210, upon energizing, at armature 211 completes the circuit for connecting relay 230 across the calling subscriber's loop; at armature 212 completes a circuit through the upper winding of relay 220 to maintain this relay in energized position; at armature 213 prepares a point in the connector test circuit; and 40 at armature 214 prepares a point in the impulsive circuit to the connector motor magnet 357. Relay 230 is now maintained over the calling loop over the following circuit: from ground through the lower winding of relay 230, armature 226, armature 206, conductor 165, wiper 155, conductor 102 over the calling subscriber's loop to conductor 101, wiper 151, conductor 164, armatures 201 and 211, and through the upper winding of relay 230 to battery. Line-cut-off relay 50 103 energizes over the previously traced circuit to operate armatures 104, 106 and 108 in their second step. At armatures 104 and 108 relay 103 disconnects the windings of relay 103 and ground from the subscriber's line conductors 101 and 102 and at armature 106 disconnects ground from common start conductor 9.

When the start conductor 9 is no longer grounded, relay 420 deenergizes and at armature 421 opens the circuit to relay 400. At armature 60 422 relay 420 again short circuits the resistance 423 to complete a circuit for energizing the distributor motor magnet 405 as follows: from ground by way of the grounded start conductor 227, bank contacts and wiper 414, armature 422, 65 interrupter springs 404 and through the winding of motor magnet 405 to battery. This circuit is the circuit by means of which the finder connector distributor preselects idle finder connector links. Motor magnet 405 is intermittently energized and deenergized over this circuit as long as wiper 414 encounters a grounded bank contact. Relay 400, upon deenergizing, at 70 armature 401 opens a point in the finder test circuit; at armature 403 opens a point in the circuit to the finder motor magnet 168; at arm-

ture 402 and its working contacts opens the circuit of slow-to-release relay 410; and at its resting contact completes a circuit by way of armature 411 for maintaining the motor magnet 405 in energized position during the interval 5 the slow-to-release relay 410 is energized. Motor magnet 405, upon energizing, positions its pawl preparatory to stepping the wipers of the distributor and at interrupter springs 404 opens the preselecting circuit previously traced. Slow-to-release relay 410 deenergizes after an interval 10 and at armature 411 opens the circuit of motor magnet 405 whereupon the motor magnet deenergizes and advances the wipers one step into engagement with the bank contact associated 15 with the next finder connector link.

In case this finder connector link is busy there will be ground on the guard conductor corresponding to conductor 227, with the result that the preselecting circuit to motor magnet 405 is 20 completed to cause the wipers to be set into engagement with the bank contact of the next finder connector link. Motor magnet 405 is intermittently operated over its preselecting circuit until wiper 414 no longer encounters a 25 grounded guard conductor, thereby indicating an idle link. When wiper 414 loses ground no circuit is completed for magnet 405 and therefore the wipers of the distributor stop in engagement with the bank contact associated with an 30 idle finder connector link.

In case all of the finder connector links are busy then each busy link has removed its individual ground from the common lead 216 to provide a stop position for the wipers of the distributor to prevent their continuous operation during this busy condition. This stop position is shown as the last or fifth position accessible to test wiper 414 and such position is normally grounded as long as any one of the finder connector links is idle. The circuit for grounding this position extends from ground by way of armature 204, armature 213 and resting contact, conductor 216, to the stop position or fifth bank contact accessible to wiper 414. This stop position is therefore grounded as long as any one of the links is idle and ground is removed therefrom only when all of the links are busy to provide a stop position for the wipers of the distributor. 50

Considering now the case in which all of the finder connector links are busy, then the wipers of the distributor would be in engagement with their fifth or stop position contact. In case a call is initiated at this time start relay 420 is 55 energized over the following circuit: from ground on the finder start conductor 9, through the winding of relay 420, armature 422, interrupter springs 404, and through the winding of motor magnet 405 to battery. Relay 420 alone energizes over this circuit; at armature 421 it completes a circuit for relay 400; and at armature 422 removes the short from around resistance 423, thereby inserting this resistance in series with relay 420. Relay 420 is therefore maintained over the circuit including the resistance 60 423 as long as the finder start conductor 9 is grounded.

As soon as one of the finder connector links becomes idle then the busy common conductor 70 216 is grounded, with the result that relay 420 is short circuited from ground on the busy common conductor 216 extending by way of wiper 414 and ground on the start conductor 9. Magnet 405 is marginal and will not energize in se- 75

ries with resistance 423 from grounded start conductor. When relay 420 deenergizes, said relay at armature 422 completes the circuit for energizing magnet 405 over the following circuit: 5 from grounded busy common conductor 216, wiper 414, armature 422, interrupter springs 404, and through the winding of magnet 405 to battery. Magnet 405 intermittently operates until test wiper 414 finds the idle connector link.

10 Considering now the case in which all of the finder connector links are busy and the distributor wipers are in stopping position, it will now be assumed that one of the links becomes idle at a time when no call is being made. In 15 this case as soon as the busy common conductor 216 is grounded the circuit for energizing motor magnet 405 is completed by way of wiper 414 and armature 422. Magnet 405 operates in the same manner as previously described until the 20 wiper 414 finds the idle connector link.

Returning now to the link circuit at a time when the calling line is found and relays 220 and 210 have been operated, dial tone is connected by the operation of these relays to the 25 calling subscriber's line as follows: from dial tone conductor 390, twenty-fifth bank contact or normal position of connector wiper 356 and said wiper, conductor 239, resting contact and armature 253, the tone condenser TC, lower talking condenser, and from thence over the calling 30 substation loop as previously traced for relay 230. When the calling subscriber hears the well-known dial tone, such subscriber will dial the number assigned to the desired subscriber, which 35 number may comprise one, two, or three digits.

Assuming now that subscriber S desires to be connected to subscriber S' shown in Fig. 3, and since the number of subscribers S' is "6", the 40 calling subscriber will thereupon dial the digit "6". In response to the operation of the calling device CD in accordance with the digit "6" the circuit to line relay 230 is interrupted six times, thereby causing the line relay 230 to be deenergized a corresponding number of times. Relay 45 230 thereupon deenergizes for each impulse and at armature 231 and its resting contact temporarily opens the circuit to slow-to-release relay 210, which, however, is slow to deenergize and is therefore maintained energized during the 50 pulsing period. At armature 231 and resting contact, relay 230 transmits an impulse to the connector motor magnet 357 upon each deenergization. This circuit may be traced as follows: from ground by way of armature 205, armature 231 and resting contact, armature 214, armature 252, armature 296, conductor 235, and through the winding of relay 357 to battery. A branch of this circuit extends from armature 55 296 by way of armature 223 and the lower winding of series relay 270 to battery for energizing the latter relay during the pulsing period.

Connector motor magnet 357, upon energizing, 60 positions its pawl preparatory to stepping the wipers of the connector. Relay 270, upon energizing, at armature 271 opens a point in the circuit to relay 200; at armature 272 opens a point in the circuit to switching relay 290, and also prepares a point in the circuit for combined 65 busy and back bridge relay 250; at armature 273 short circuits its upper winding to make this relay slow-to-release so that it will be maintained in energized position during the pulsing period; and at armature 274 closes a shunt around armature 252 to prevent the 70 operation of busy relay from opening the pulsing

circuit to the motor magnet 357. When relay 230 energizes after each impulse, the circuit to connector motor magnet 357 is opened, with the result that this magnet steps the wipers of the connector one step for each deenergization. In 5 response to the six impulses transmitted thereto, magnet 357 steps the wipers of the connector from in engagement with their normal bank contacts into engagement with their sixth bank contacts, or the contacts terminating the called 10 line.

The operation of the finder connector at this time depends upon whether the called line is busy or idle. In case the called line is busy, then ground will be encountered by test wiper 15 353, with the result that the combined busy relay and back-bridge relay 250 is energized over the following circuit: from ground on the busy test conductor of the called line, sixth bank contact engaged by wiper 353, conductor 234, 20 armature 272 and working contact, armature 295, resistance 254, and through the upper winding of relay 250 to battery. At armature 251 relay 250 opens a point in the testing circuit extending through the upper winding of switching 25 relay 290 and at its working contact prepares a locking circuit for busy relay 250. At armature 252 relay 250 opens a point in the impulsive circuit to magnet 357 and at armature 253 connects the busy tone to the calling line. Shortly 30 after the impulses cease series relay 270 deenergizes and at the normally closed springs controlled by armature 272 completes the locking circuit for busy relay 250 as follows: from ground by way of armature 204, armature 213 and working contact, armature 251 and working contact, through the normally closed springs controlled by armature 272, armature 295, resistance 254, and through the upper winding of busy relay 250 to battery. The busy tone is transmitted to 40 the calling subscriber over the following circuit: from a busy tone, armature 297, working contact and armature 253, tone condenser TC, lower talking condenser, and thence over the heavy talking conductors to the calling line.

When the calling subscriber hears the busy tone, such subscriber will replace his receiver to cause the release of the established connection in a manner to be more fully described herein-after.

Assuming now that the called line was idle instead of busy, then no circuit is completed for busy relay 250 because the test conductor of the called line is not grounded. Series relay 270 deenergizes shortly after the impulsive period 55 and at armature 272 completes the circuit for energizing the switching relay 290 in series with line-cut-off relay 303 of the called line as follows: from ground by way of armature 204, armature 213 and working contact, armature 251 60 and resting contact, through the upper winding of switching relay 290, resting contact and armature 272, conductor 234, test wiper 353 in engagement with its sixth bank contact, conductor 310, and through the lower winding of two-step, 65 line, and cut-off relay 303 to battery.

Relay 303 energizes over the above-traced circuit and operates its armatures in their second step to disconnect itself and ground from the line conductors of the called line. Switching 70 relay 290, upon energizing, at armature 292 prepares a point in the transfer circuit; at armature 293 completes a locking circuit through its lower winding by way of armature 283 and grounded armature 212; at armature 294 con- 75

nects direct ground to wiper 353 to mark the called line busy to other connectors having access thereto; at armature 295 opens a point in the circuit to busy relay 250; at armature 296 5 opens a point in the self-restoring circuit of connector motor magnet 357; at armature 297 opens a point in the busy tone circuit; and at armatures 291 and 298 connects interrupted generator to the called line. The circuit for signalling the called subscriber may be traced as follows: from interrupted generator by way of 10 resting contact and armature 263, armature 298, conductor 239, wiper 356 in engagement with its sixth bank contact, conductor 302, through the 15 ringer bells RB and ringing condenser at the substation, over conductor 301 and from thence to the sixth bank contact engaged by wiper 351 and said wiper, conductor 232, armature 291, armature 261 and resting contact, and 20 through the upper winding of ring-cut-off relay 260 to battery.

When the called subscriber answers, ring-cut-off relay 260 is energized over the called subscriber's loop, this time including the transmitter T and the upper switchhook springs SH in place of the ringer RB and the ringing condenser. At armature 262 relay 260 completes a locking circuit through its lower winding from 25 grounded armature 212 and at armatures 261 and 263 opens the ringing circuit and at the working contacts of these armatures connects the called line in series with differential relay 244 and relay 250.

Relay 250 is energized over the called subscriber's loop as follows: from ground by way 35 of armature 212, armature 262, through the lower winding of relay 250, through the lower winding of differential relay 244, working contact and armature 263, from thence over the previously traced circuit through the called subscriber's loop to armature 291, armature 261 and working contact, through the upper winding of differential relay 244 and through the upper winding of relay 250 to battery. Relay 250 40 alone is energized over this circuit and furnishes talking battery through both its windings to the called subscriber. Differential relay 244 does not energize over the previously traced circuit because the two windings are equal and oppose 45 each other. The talking circuit between the local subscribers' lines are now completed over the heavy talking conductors.

After conversation and responsive to the calling subscriber S replacing his receiver, line 55 relay 230 deenergizes when its circuit is opened at the switchhook springs SH and said relay at armature 231 opens the circuit to release relay 210. After an interval slow-to-release relay 210 deenergizes and at armature 211 opens a point 60 in the talking circuit to the calling line. At armature 213 relay 210 connects grounded armature 204 to the busy common conductor 216 to prevent the finder connector distributor from stopping on its stopping position as previously 65 described, and at armature 212 opens the holding circuits of relays 290, 260, and 220. Relay 220, upon deenergizing, at armature 224 removes one of the multiple ground connections from guard conductor 227, which conductor at this time is 70 grounded by connector wiper 354 in engagement with its multiple contacts connected to ground. At armature 225 relay 220 disconnects ground from conductor 163 and test wiper 153 to remove the busy guarding potential, and at armature 75 226 opens a further point in the talking circuit

and prepares the circuit through the lower winding of relay 220.

Switching relay 290, upon deenergizing, at armatures 291 and 298 opens points in the talking circuit to the called line and the circuit of relay 250 in case the called subscriber has not replaced his receiver; at armature 293 relay 290 opens its own locking circuit; at armature 294 opens the circuit to line-cut-off relay 303 and removes the busy ground potential; and at armature 296 completes a self-restoring circuit for the connector. This self-restoring circuit may be traced as follows: from ground by way of the multiplied contacts engaged by wiper 354, conductor 227, armature 224 and resting contact, 10 conductor 237, interrupter spring 358, conductor 236, armature 296, conductor 235, and through the winding of magnet 357 to battery. At interrupter springs 358 motor magnet 357 interrupts its own circuit to cause the magnet to operate 15 in the same manner as a buzzer to advance the wipers step by step until wiper 354 no longer encounters a grounded bank contact. Since the normal position bank contact accessible to wiper 354 is the only bank contact accessible to this 20 wiper that is not grounded, the wipers of the connector will be advanced step by step by motor magnet 357 until wiper 354 reaches its normal position. When wiper 354 reaches its normal 25 position, ground is removed from guard conductor 27 to permit this finder connector link to be preselected by the finder connector distributor shown in Fig. 4.

The local subscribers are divided into three groups, the first group having only a single call 35 digit in their telephone numbers, the second group having two call digits in their telephone numbers, and the third group having three digits in their telephone numbers. The first digit in the telephone numbers of all second-group subscribers 40 is the digit "0", and the first and second digits of the subscribers' telephone numbers in the third group are the digits "0"—"0".

In order to call a subscriber in the second group the calling subscriber initiates the call in 45 the same manner as previously described to cause a finder-connector link to be connected to the calling line. In response to dial tone the calling subscriber dials the digit "0" to step the connector to the tenth bank contacts, which contacts are dead contacts and do not complete any 50 circuits. Since neither ground nor battery is encountered by test wiper 253, the connector remains in this position until the receipt of the second digit. In response to the calling subscriber dialling the second digit the wipers of the connector are stepped from the tenth bank contacts a number of steps corresponding to the digit dialled and into engagement with the bank contact terminating the called line in the second 55 group. The connection is now completed by the connector in the same manner as previously described. In order to call a subscriber in the third group the calling subscriber dials the digit "0" for the first digit, the digit "0" for the second digit, and then the units digit of the called line to cause the wipers of the connector to come to a rest in engagement with the bank contacts terminating the called line.

Incoming calls

It will now be assumed that an incoming trunk call is received over conductors 794 and 795 from the distant exchange. When an incoming call is received over conductors 794 and 705, relays 75

770 and 780 operate. Relay 780 is a very high wound relay and operates in response to either the ringing current or during the silent period, while relay 770 is an alternating current relay 5 which operates only in response to ringing current. The circuit for energizing alternating current relay 770 may be traced as follows: from generator at the main exchange, conductor 794, condenser and upper winding of alternating current relay 770, resting contact and armature 773, conductor 694, armature 666, conductor 695, armature 744, conductor 795, back to generator at the main exchange. Relay 780 is energized over the following circuit: from ground at the 10 main exchange, or generator, extending over conductor 794 through the winding of relay 780, armature 744, and by way of conductor 795 back to main exchange battery. At armature 781 relay 780 completes an obvious circuit for energizing slow-to-release relay 750. Relay 770, upon energizing, at armature 771 prepares a point in its own locking circuit; at armature 772 disconnects ground from conductor 374 to mark this 15 trunk as calling in the bank of the trunk distributor shown in Fig. 3; at armature 772 and working contact grounds conductor 370 to energize relay 314 over an obvious circuit; at armature 773 and resting contact disconnects the upper winding of relay 770; and at its working 20 contact bridges the alternating current signalling relay 760 and condenser C across the trunk conductors 794 and 795 by way of armatures 666 and 744 and conductors 694 and 695.

Relay 750, upon energizing, at armature 751 completes a circuit for energizing slow-to-release relay 790; at armature 752 completes a circuit for energizing relay 730; at armature 753 prepares a point in its own locking circuit; at armature 754 completes the locking circuit through 25 the lower winding of relay 770 by way of armatures 623 and 633 and their resting contacts over conductor 628; and at armature 755 prepares a substitute circuit for alternating current signalling relay 760. At armature 791 and its resting 30 contact relay 790 disconnects one of the ground connections from the busy common conductor 376 over which the busy relay 361 is normally held energized as long as one of the trunk lines is idle. At armature 791 and its working contact relay 790 connects ground to conductor 373 to operate the trunk distributor in case the wiper 35 is in engagement with the bank contact terminating in this particular conductor. At armature 792 relay 790 prepares a point in the circuit for energizing relay 630. Relay 730, upon energizing, at armature 731 disconnects relay 720 and prepares a point in the talking circuit; at armature 732 connects another ground to relay 792; and at armature 733 prepares a point 40 in its own locking circuit. Relay 314, upon energizing, at armature 320 disconnects ground from conductor 371 to remove the busy condition and connects battery through the windings of relays 315 and 316 to the trunk answering bank contact No. 8 in the connector bank accessible to wiper 353.

Alternating current signalling relay 760 operates from ringing current transmitted from the main exchange and at armature 762 maintains the circuit of relay 750 independent of armature 781. At armature 761 alternating current signalling relay 760 connects battery to conductor 624, through resistance 763, to signal the attendant or to operate the common trunk signal lamps located throughout the premises de-

pendent upon whether the attendant signal key SK is operated or at normal.

Assuming that the key SK is normal, then relay 507 is energized over the following circuit: from ground through the winding of relay 507, normally closed springs of key SK, common conductor 609, resting contact and armature 662, conductor 624, armature 761, and through resistance 763 to battery. At armature 508 relay 507 completes the circuit for lighting the 10 trunk signal lamps located throughout the premises to enable the non-restricted subscribers to answer the incoming trunk call.

The trunk distributor shown in Fig. 3 is arranged to normally preselect an idle trunk for 15 use in an outgoing call, and in case the outgoing test wiper 335 is in engagement with the bank contact terminating conductor 373 of the trunk shown in Fig. 7 when such trunk is seized for an incoming call, the trunk distributor motor 20 magnet 333 is energized as follows: from grounded conductor 373, bank contact and wiper 335, resting contact and armature 322, armature 328, interrupter springs 334, and through the winding of motor magnet 333 to battery. 25 Motor magnet 333 operates to position the pawl preparatory to stepping the wipers of the distributor and at its interrupter springs 334 interrupts its own circuit. Magnet 333 thereupon deenergizes and advances the wipers of the distributor into engagement with the bank contacts terminating the next trunk line. In case this trunk line is idle, wiper 335 does not encounter a grounded bank contact and the wipers remain in this position. In case the next trunk 30 line is busy, then ground is encountered by the wiper 335 to again advance the wipers to the next trunk or until an idle trunk is found.

Any non-restricted local subscriber equipped with a push-button, such as PB, may answer 40 this trunk call by removing his receiver and dialling the digit "8" to position the connector of the finder-connector link on the trunk answering position 8.

In response to subscriber S removing his receiver to answer this trunk call, an idle finder connector link is connected to this subscriber's line and in response to the receipt of dial tone such subscriber will dial digit "8" to answer the trunk call. In the same manner as previously 45

described the connector wipers are stepped into engagement with their eighth bank contacts and when series relay 270 deenergizes after the impulsive period a circuit is completed for energizing relays 290 and 316 in series as follows: 50 from ground by way of armature 204, armature 213 and working contact, armature 251 and resting contact, through the upper winding of switching relay 290, resting contact and armature 272, conductor 234, test wiper 353 in engagement with its eighth bank contact, conductor 371, armature 320 and its working contact, through the winding of marginal relay 315 and through the upper and lower windings of relay 316 to battery. Relay 315 is marginal and will 55 not operate in series with the lower high-resistance winding of relay 316. Relay 290, upon energizing, at armature 292 prepares a point in the circuit for the local release relay 200 and for marking the line of subscriber S as answering a 60 trunk call in the trunk finder bank. At armature 293 relay 290 again completes its locking circuit and at armature 294 grounds test wiper 353.

Relay 316, upon energizing, at armature 326 75

opens the initial energizing circuit for relay 363 to prevent its operation in case an outgoing call is originated before the incoming call is completed. At armature 325 relay 316 completes a circuit for shunting out the lower high-resistance winding of relay 316 only in case relay 363 is not energized in a preceding outgoing call. When the lower winding of relay 316 is shunted by battery at armature 369, marginal marking relay 315 thereupon energizes in series with relay 316. Relay 315, upon energizing, at armature 321 grounds conductor 312 for a purpose to be described later; at armature 322 switches the test circuit from the outgoing test wiper 335 to the incoming test wiper 336 to cause the trunk distributor to find the calling trunk. At armature 323 relay 315 grounds conductor 380 to prepare a circuit for the local release relay 200 and likewise marks the line answering this trunk call, or line S, in the trunk finder bank. At armature 324 relay 315 closes a circuit for energizing relay 317 when the calling trunk is found by the trunk distributor.

Considering now that the wipers of the trunk distributor are in the position shown in the drawings, then relay 317 is short circuited from ground encountered on the multiple contacts by wiper 336 by way of armature 322 and armature 324. A branch of this circuit extends by way of armature 328 and interrupter springs 334 through the winding of motor magnet 333 for operating the latter magnet. In the same manner as previously described, magnet 333 steps the wipers of the trunk distributor and interrupts its own circuit until wiper 336 no longer encounters a grounded contact, or in this case until wiper 336 encounters the contact terminating conductor 374, from which ground has been removed by the operation of relay 710. It should possibly be stated at this time that the motor magnet 333 is marginal and will not energize in series with either resistance 329 or the winding of relay 317.

When wiper 336 no longer encounters a grounded bank contact, the short circuit around relay 317 is removed, with the result that this relay now energizes over the following circuit: from ground by way of armature 324, winding of relay 317, armature 328, interrupter springs 334, and through the winding of magnet 333 to battery. Relay 317 alone energizes over this circuit and at armature 327 completes a circuit for energizing relay 318, and at armature 328 removes the short circuit from around resistance 329 to prevent the energization of magnet 333 in case conductor 374 becomes grounded. At armature 330 relay 318 completes a circuit for energizing relay 319 and at armature 331 grounds conductor 629 to energize relay 650 in the trunk. At armature 332 relay 319 prepares a point in the circuit for magnet 333.

The circuit for energizing relay 650 may be traced as follows: from ground by way of armature 331, wiper 337 in engagement with its sixth bank contact, conductor 629, and through the winding of relay 650 to battery. At armature 651 relay 650 prepares a circuit for later maintaining relay 670 in energized position; at armature 652 prepares the trunk test circuit for energizing relays 670, 660, and 200 in series; at armature 653 disconnects a point in the transfer circuit; at armature 654 completes a circuit for energizing the trunk finder motor magnet 568; and at armature 655 prepares a point in the bridge across conductors 561 and 565. The cir-

cuit for energizing magnet 568 may be traced from grounded armature 654 by way of armature 671 and resting contact, conductor 567, and through the winding of trunk finder motor magnet 568 to battery. ⁵

Motor magnet 568 energizes and positions its pawl preparatory to stepping the wipers of the trunk finder and at its springs 569 completes the circuit for energizing relay 670 over the following circuit: from ground by way of springs 569, conductor 566, and through the upper winding of stepping relay 670 to battery. Stepping relay 670 energizes over the above-traced circuit and at armature 671 and its resting contact opens the circuit to the trunk finder motor magnet 568 and at its working contact connects another ground to conductor 692. Motor magnet 568 deenergizes when its circuit is opened by relay 670, and, upon deenergizing, advances the wipers of the trunk finder one step and likewise opens the circuit of stepping relay 670 at springs 569. At armature 671 stepping relay 670 again completes the circuit for energizing motor magnet 568 and the motor magnet 568 at springs 569 again completes the circuit for stepping relay 670. Motor magnet 568 and stepping relay 670 intermittently operate as described until test wiper 552 of the trunk finder finds the marked bank contact, at which time a circuit is completed for energizing relays 200 and 660 as well as maintaining stepping relay 670 in energized position. This circuit may be traced as follows: from ground by way of armature 323, conductor 380, eighth bank contact engaged by wiper 352 and said wiper, conductor 233, armature 282 and resting contact, armature 292, lower winding of local release relay 200, conductor 162, wiper 152 in engagement with its fifteenth bank contact or the bank contact corresponding to the calling line answering this trunk call, conductor 28, fifteenth bank contact in the trunk finder accessible to wiper 552 and said wiper, conductor 562, resting contact and armature 621, armature 652, through the upper winding of relay 660 and through the lower winding of stepping relay 670 to battery. ²⁵

Stepping relay 670 is maintained energized over this circuit and relays 200 and 660 are energized thereover. At armatures 661 relay 660 completes a circuit by way of armature 651 ⁵⁰ through the upper winding of stepping relay 670 for maintaining this relay in energized position; and at armature 662 and resting contact opens a point in the circuit for operating the signal relay 507. At armature 663 relay 660 completes a circuit by way of resting contact and armature 683 for energizing slow-to-operate relay 690; at armature 664 completes a circuit for energizing slow-to-release relay 630; and at armature 665 connects conductor 693 to conductor 696 to provide another circuit for signal relay 760 when armature 666 disconnects conductor 694 from 695. The circuit for energizing relay 630 may be traced from grounded conductor 692 grounded at either armature 792 or by way of armatures 654 and 671 and thence by way of armature 664 through the winding of relay 630 to battery. At armature 631 relay 630 closes a point in the upper talking conductor; at armature 632 opens a point in the circuit to relay 640; at armature 633 closes a circuit for maintaining relay 660 energized through its lower winding from grounded armature 623; at armature 634 grounds conductor 564 and wiper 554 to make the line answering this trunk call busy and for holding the combined ⁶⁵ 70 75

line and cut-off relay 103 in energized position; at armature 635 completes a bridge across conductors 561 and 565 including the resistance 637 and armature 655; and at armature 636 closes a point in the lower talking conductor.

In the local finder connector link local release relay 200 energizes in series with relay 660 and at armatures 201 and 206 opens the line conductors extending to line relay 230, whereupon the latter relay now deenergizes. At armature 203 relay 200 closes a locking circuit through its upper winding as long as slow-to-release relay 210 remains energized; at armature 204 opens a point in the original energizing circuit of relay 290 or the locking circuit of the busy relay 250 if the latter relay is energized; and at armature 205 opens a point in the impulsing circuit and also opens the circuit of relay 210. Relay 230 deenergizes and at armature 231 opens a further point in the circuit of slow-to-release relay 210. After an interval slow-to-release relay 210 deenergizes to cause the deenergization of switching relay 290 and causes the connector to release in the same manner as previously described.

When relay 290 deenergizes and at armature 294 removes ground from wiper 353, the circuit to relays 315 and 316 is opened, causing the latter relays to deenergize. Relay 316 deenergizes and at armatures 325 and 326 allows other trunk calls to be originated and answered. Relay 315 deenergizes and disconnects ground from conductor 372. At armature 322 relay 315 disconnects the incoming test wiper 336 and connects up the outgoing test wiper 335 to cause the trunk distributor to hunt for and select an idle trunk. At armature 323 relay 315 disconnects marking ground from conductor 380 to open the original energizing circuit of relays 200 and 660; and at armature 324 opens the circuit to relay 317 which now deenergizes. At armature 327 relay 317 opens the circuit of relay 318 which now deenergizes and at armature 328 short circuits the resistance 329 to permit the energization of magnet 333. At armature 330 and its working contact relay 318 opens the circuit of slow-to-release relay 319 and at its resting contact completes a circuit for energizing motor magnet 339 by way of armature 332 as long as the slow-to-release relay 319 is operated. At armature 331 relay 318 removes ground from conductor 629 to cause the deenergization of relay 650. Slow-to-release relay 319 deenergizes after an interval and opens the circuit of motor magnet 333 at armature 332, thereby causing the magnet upon its deenergization to advance the wipers into engagement with the next bank contact. Since the outgoing test wiper 335 is connected to the grounded multiple contacts at this time, the magnet 333 intermittently operates as previously described to step 60 the wipers of the trunk distributor in search of an idle trunk.

Assuming that the trunk last used, was the last available trunk then ground is disconnected from the busy common conductor 376 to provide a stopping position for the trunk distributor wipers to prevent their continuous operation as long as all of the trunk lines are busy. Assuming, however, that one or more of the trunk lines are idle, then busy common conductor 376 is 70 grounded and the wipers are advanced until test wiper 335 loses ground, such condition indicating an idle trunk. The normally energized all-trunk-busy relay 361 also deenergizes when all of the trunks are busy when ground is removed 75 from the busy common conductor 376. At arma-

ture 364 relay 361 opens the circuit to relays 362 and 363 to prevent their energization when a local subscriber attempts to originate an outgoing call, and at the resting contact of armature 364 grounds the ninth bank contact accessible to said wiper 353 to cause the finder-connector links to transmit the busy tone to a calling subscriber attempting to originate an outgoing trunk call. At armature 366 relay 361 connects busy tone to conductor 377 to transmit busy tone to a calling local subscriber when said subscriber initiates an outgoing call just prior to or simultaneously with the last trunk being seized on an incoming call. In this case the conductor 378 was not grounded and the connector of a 15 finder connector link switches through to cause the seizure of the last idle trunk. At the same time, however, the trunk was seized for an incoming call and therefore since incoming calls are given preference over outgoing calls the party 20 originating the outgoing call is given a busy tone over conductor 377.

When relay 630 energizes in response to the operation of relay 660 at the time the trunk finder finds the answering local line, relay 630 25 first operates its preliminary make armature 635 before operating its other armatures to close a ring-cut-off bridge across the upper and lower talking conductors extending to the distant main exchange. This ring-cut-off bridge, comprising 30 armature 631, resistance 637, and armatures 655, 635, and 636 is only temporarily placed across the trunk conductor to cause the disconnection of ringing current at the main exchange in the well-known manner and to reduce the click in 35 the answering subscriber's receiver, since the subscriber's line at this time is also connected in bridge of the trunk line. The operation of armature 633 at its resting contact also opens the locking circuit of relay 770 which deenergizes 40 to open the circuit of relay 314 at the working contact of armature 772, and to ground the marking conductor 374 at the resting contact of armature 772. Relay 314 deenergizes and at armature 320 opens the circuit to relays 315 and 45 316 and grounds conductor 371 to place busy potential on the answering trunk position terminating in the eighth bank contact accessible to wiper 353.

When relay 650 deenergizes in response to the 50 deenergization of relay 318 relay 650 at armature 651 opens the circuit of relay 670 which thereupon deenergizes, at armature 652 opens the test circuit through the relays 660 and 670; at armature 654 opens a point in the circuit to 55 motor magnet 568 to prevent its operation; and at armature 655 opens the ring-cut-off bridge previously referred to. Relay 670 deenergizes without result since the circuit to motor magnet 568 is opened at armature 654.

At this time the local finder connector link has released and is available for use in other local calls, while in the trunk circuit shown in Figs. 6 and 7 the following relays are operated: relays 630, 660, 690, 730, 750, 780, and 790. The line 65 of substation S is now connected to the distant main exchange over the following circuit: from the substation S, conductors 101 and 102 terminating in the trunk finder bank, wipers 551 and 555, conductors 561 and 565, armatures 631 and 636, through the upper and lower windings of differential relay 614, conductors 616 and 691, through the normally closed springs controlled by armatures 701 and 705 through the talking condenser and through the upper and lower 75

windings of series relay 713 in multiple, resting contact and armature 723, working contact and armature 731, and over trunk conductors 784 and 795 to the distant main exchange.

5 Relay 614 in the circuit just traced is a differential relay and therefore does not operate its armature when both windings are energized. Series relay 713 energizes over the above traced circuit and at armature 714 completes the circuit for energizing relay 740. At armature 741 relay 740 maintains relay 790 energized, at armature 742 completes a locking circuit for relay 730, at armature 743 completes a locking circuit for relay 750, and at armature 744 disconnects relay 780 from in bridge of trunk conductors 794 and 795 to cause the latter relay to deenergize. The deenergization of relay 780 is without effect at this time since relay 750 is now held energized over its locking circuit. Subscriber S now converses with the calling subscriber over the heavy talking conductors and both the calling and the called subscribers receive their talking battery from the main exchange.

The release of incoming trunk connections is under control of the calling main-exchange subscriber or the main-exchange operator. The replacement of the receiver by subscriber S opens the circuit of series relay 713 which accordingly deenergizes and opens the circuit of relay 740. At armature 744 relay 740, upon deenergizing, reconnects the high resistance relay 780 across the trunk conductors to cause its energization if the calling main-exchange subscriber has not hung up. At armature 781 relay 780 maintains slow to release relay 750 operated to prevent the deenergization of relay 730. If the distant main-exchange operator desires to re-signal subscriber S she may do so by applying ringing generator to the trunk conductors 794 and 795. The alternating current signalling relay 760 re-operates over a circuit including armatures 755 and 665, but does not operate the general trunk signals because the signalling circuit is open at armature 662. Ringing current transmitted from the main exchange extends over the talking circuit previously traced to the line of subscriber S to operate the ringer RB at this subscriber station and therefore directly signal subscriber S.

When the distant calling subscriber or the distant operator disconnects at the main exchange, relay 780 deenergizes and at armature 781 opens the circuit to slow-release relay 750. At armature 751 relay 750, upon deenergizing, opens one of the circuits extending to relay 790; at armature 752 opens the circuit to relay 730 which now deenergizes; and at armature 755 opens the circuit of alternating current signalling relay 760. At armature 731 relay 730, upon deenergizing, opens a point in the talking circuit and at armature 732 opens the circuit of slow-to-release relay 790 which now deenergizes. At armature 791 relay 790 grounds the busy common conductor 376 and disconnects ground from conductor 373 to allow this trunk to be used in an outgoing call. At armature 792 relay 790 opens the circuit of relay 630 which now deenergizes. At armatures 631 and 636 relay 630 opens a further point in the talking circuit; at armature 633 opens the circuit of relay 660 which deenergizes; and at armature 634 removes the busy ground from the multiplied test conductor of the called line and likewise causes the release of the combined line and cut-off relay 103. At armature 662 relay 660, upon deenergizing, reestablishes the signalling circuit for operating

the general trunk signals; at armature 663 opens the circuit of relay 690 which deenergizes; at armature 664 opens a further point in the circuit of relay 630; and at armature 665 opens the circuit for reoperating the alternating current signalling relay 760. At armature 691 relay 690, upon deenergizing, removes ground from conductor 621. At this time all of the relays in the trunk are at normal position and the trunk may be used on other trunk calls for either incoming or outgoing calls.

Outgoing calls

Any non-restricted, local subscriber may originate an outgoing trunk call by removing his receiver and dialing the digit "9" to position the connector of a local finder connector link on the trunk calling position 9. In response to the subscriber S removing his receiver to originate a trunk call, an idle finder connector link is connected to this subscriber's line and, in response to the receipt of dial tone, subscriber S dials the digit 9 to operate the connector wipers into engagement with their ninth bank contact in the same manner as previously described.

In case all of the trunks are busy, then busy relay 361 in the trunk distributor is deenergized and ground is connected to trunk call position 9 engaged by wiper 353 to cause the operation of the busy relay in the local finder connector link. The operation of the busy relay, such as relay 250 in the link shown in Fig. 2, causes the busy tone to be transmitted to the calling line in the same manner as previously.

In case, however, one or more of the trunks are idle, then the busy relay 361 is in energized position and a circuit is completed for energizing the switching relay, such as switching relay 290 in the finder connector link, in series with relays 362 and 363 in case the trunk distributor is not in use answering an incoming trunk call. Relay 362 is marginal and will not energize in series with the upper winding of relay 363. The circuit for energizing switching relay 290 and relay 363 may be traced as follows: from ground by way of armature 204, armature 213 and working contact, armature 251 and resting contact, through the upper winding of switching relay 290, resting contact and armature 272, conductor 234, test wiper 353 in engagement with its ninth bank contact, conductor 378, armature 364 and its working contact, through the winding of marginal relay 362, through the lower and upper windings of relay 363, to battery at armature 326.

In case the trunk distributor is in use in answering an incoming trunk call, relay 316 is operated and the circuit just traced is not completed until relay 315 deenergizes as previously described. At armature 369 relay 363 shunts out the upper high-resistance winding of relay 363 to permit the energization of marginal marking relay 362. In a similar manner the operation of armature 369 prevents the operation of marginal marking relay 315 in case some subscriber subsequently attempts to answer an incoming trunk call when the trunk distributor is in use. Relay 362, upon energizing, at armature 367 marks the calling line in the banks of the trunk finders over the following circuit: from ground by way of armature 367, conductor 379, ninth bank contact and wiper 352, conductor 233, armature 282 and resting contact, armature 292, through the lower winding of local release relay 200, conductor 162, wiper 152, conductor 28 multiplied to the trunk finders to the fifteenth bank con-

tact accessible to wiper 552. At armature 368 relay 362 completes the circuit for energizing relay 317 over the following circuit: from ground by way of armature 368, winding of relay 317, armature 328, interrupter springs 334, and through the winding of motor magnet 333 to battery. Motor magnet 333 is marginal and will not energize in series with relay 317 or resistance 329. Since the trunk distributor is normally arranged to preselect idle trunks for use in outgoing calls, it is assumed that the trunk distributor has therefore preselected the trunk shown in Figs. 6 and 7 when the outgoing trunk call was originated.

15 In case the wiper 335 was in engagement with a grounded bank contact, the relay 317 would have been short circuited to prevent its operation and the motor magnet would have operated the wipers of the trunk distributor until an idle 20 trunk was found. At armature 327 relay 317 operates relay 318 and at armature 328 opens the short circuit around resistance 329. At armature 330 relay 318 completes the circuit for relay 319 and at armature 331 completes the circuit for energizing relay 650 in the preselected 25 idle trunk as follows: from ground by way of armature 331, wiper 337 in engagement with its first bank contact, conductor 629 and through the winding of relay 650 to battery.

30 In response to the operation of relay 650, the trunk finder is operated in the same manner as previously described to find the marked bank contact, at which time a circuit is completed for energizing the local release relay 290 in the 35 finder connector link and relay 660 in the trunk as well as maintaining relay 670 in operated position. The operation of the relay 660 in the same manner as previously described causes the operation of relays 690 and 638. In the local 40 finder connector link local release relay 290 is energized and causes the local finder connector link to release in the same manner as previously described. When switching relay 290 in the local finder connector link deenergizes, ground is removed from wiper 353, thereby opening the circuits of relays 362 and 363. At armature 369 relay 363 now permits any incoming calls to be answered by connecting battery to armature 325. At armature 367 the deenergization 45 of relay 362 disconnects marking ground from conductor 378. At armature 368 relay 362 opens the circuit of relay 317 which deenergizes to allow the motor magnet to step the wipers of the trunk distributor in search of an idle trunk.

50 At armature 331 relay 318, upon deenergizing, opens the circuit of relay 650.

The operation of the trunk relays are slightly different dependent upon whether the trunk conductors 794 and 795 extend to a manual or an automatic exchange. In either case, ground is disconnected from trunk conductor 794 at the main exchange, while conductor 795 extends to a signalling relay and negative battery in case of a manual exchange or extends through the line relay of an incoming line switch in case the main exchange is an automatic exchange. In addition, relay 720 in Fig. 7 is permanently short circuited in case the trunk conductors 794 and 795 extend to an automatic exchange, while the short circuit is removed from around said relay in case the trunk conductors extend to a manual exchange.

It will first be assumed that the trunk conductors extend to a manual exchange and therefore a circuit may be traced from ground through

the winding of relay 720 through the local calling subscriber's loop and from thence through the signalling relay at the main manual exchange to battery. The circuit for energizing relay 720 may be traced in detail as follows: from ground through the winding of relay 720, normally closed springs controlled by armature 731, through the upper winding of series relay 713, normally closed springs controlled by armature 701, conductor 616, through the upper winding of differential relay 614, armature 631, resistance 631, armature 655, armature 635, armature 636, through the lower winding of differential relay 614, conductor 697, normally closed springs controlled by armature 705, through the lower winding of series relay 713, resting contact and armature 723, and over conductor 795 to battery through the signalling relay at the main exchange.

The calling subscriber's loop is also connected across the talking conductors 561 and 565 to assist in energizing relays 720 and 713 and to later on maintain series relay 713 in energized position after the bridge including resistance 637 and armatures 655 and 635 is opened. The operation of the signalling relay at the main exchange signals the operator thereat in the well-known manner. Series relay 713, upon energizing over the above-traced circuit, at armature 714 completes an obvious circuit for energizing relay 740. Relay 720, upon energizing over the above-traced circuit, at armature 721 likewise completes a circuit for energizing relay 740; at armature 722 completes a circuit for connecting battery through resistance 724 through the lower winding of series relay 713 before armatures 721 and 723 are fully operated, in order to maintain the series relay 713 in energized position when relay 720 subsequently deenergizes. At armature 723 relay 720 connects direct ground to conductor 795 to maintain the main-exchange signalling relay in energized position. Slow-to-release relay 740, upon energizing, at armature 741 completes an obvious circuit for energizing relay 790; at armature 742 prepares a point in the circuit for relay 730; at armature 743 prepares a point in the locking circuit for relay 750; and at armature 744 disconnects relays 710 and 780 from in bridge of the trunk. Relay 790, upon energizing, at armature 791 and its resting contact disconnects one of the ground connections to the busy common conductor, and at its working contact grounds conductor 378 to short circuit relay 317 and cause the trunk distributor to preselect another trunk as previously described. At armature 792 relay 790 completes a circuit for holding relay 630 in energized position by way of conductor 692 and armature 664.

When the trunk distributor operates in the manner previously described to preselect an idle trunk, the circuit to relay 650 is opened, whereupon such relay now deenergizes. At armatures 651 and 652 relay 650 opens the circuit to relay 670 which now deenergizes; at armature 654 opens the original energizing circuit of relay 630, which relay is now held energized from grounded armature 792; and at armature 655 opens the local bridge across the talking conductors. Series relay 713 and slow-to-release relay 720 are now held energized over the previously traced circuit through the calling subscriber's loop. At armature 671 the deenergization of relay 670 opens a point in the original energizing circuit of relay 630.

When the manual operator at the main ex-

change answers the call, ground is connected to conductor 794, thereby completing an energizing circuit for relay 730 as follows: from ground at the main exchange by way of conductor 794, normally closed springs controlled by armature 733, armature 742, and through the winding of slow-to-release relay 730 to battery. At armature 731 relay 740 completes a point in the talking circuit and also substitutes the ground at the main exchange for ground through the winding of relay 720; at armature 732 maintains relay 790 energized; and at armature 733 completes the locking circuit for itself by way of armature 742 before opening its original energizing circuit. Relay 720, upon deenergizing, at armature 721 opens a point in the circuit of relay 740, which relay is held energized from armature 714 on the series relay 713; at armature 723 disconnects the ground from conductor 794 and completes the talking circuit; and at armature 722 disconnects battery extending through resistance 724 from the lower winding of series relay 713 after armature 723 has completed the talking circuit. Series relay 713 is maintained energized from ground at the main exchange extending by way of conductor 794, armature 731, through its upper winding and from thence over the calling subscriber's loop through its lower winding, resting contact of armature 723 and said armature, conductor 795 to battery at the main exchange. The calling subscriber is now connected to the distant operator and may converse over the heavy talking conductors to inform the distant operator of the desired subscriber. The manual operator at the distant exchange completes the connection to the desired subscriber in the well-known manner.

It will now be assumed that the trunk conductors 794 and 795 extend to an automatic exchange and therefore the operation of relay 630 completes a circuit for energizing series relay 713 and the line relay of an incoming line switch in the main exchange. This circuit may be traced as follows: from ground over the short circuiting connections of relay 720, normally closed springs controlled by armature 731, through the upper winding of series relay 713, and from thence over the local bridge including the resistance 637, the lower winding of relay 713, as previously described, over conductor 795 through the winding of the line relay in the incoming line switch to battery. At armature 714 relay 713 completes a circuit for energizing relay 740 and relay 740, upon energizing, completes a circuit for energizing relay 790 and prepares a circuit for energizing relay 730 in the same manner as previously described. The operation of relay 790 causes the trunk distributor to pre-select another idle trunk, whereupon relay 650 deenergizes as previously described. When the local bridge is opened at armature 655 by the deenergization of relay 650 the series relay 713 and the line relay in the incoming line switch at the main exchange are held energized over the calling subscriber's loop.

The operation of the line relay at the main exchange causes the line switch thereat to operate in the well-known manner to seize an idle trunk, at which time dial tone is transmitted back over conductors 794 and 795 to the calling subscriber. In addition, ground is connected to trunk conductor 794, thereby causing the energization of relay 730 to complete the talking circuit. At armature 731 relay 730 completes a direct metallic loop including the calling sub-

scriber's line to enable the local calling subscriber to operate the automatic switches in the automatic exchange in response to the operation of his calling device CD.

In response to the calling subscriber S operating his calling device CD, the automatic switches in the automatic exchange are operated in the well-known manner to complete the desired connection. Relay 713 intermittently operates during the impulsing period, but since relay 740 is slow to release the latter relay is maintained in operated position to prevent the deenergization of relay 730. Talking battery for both the calling and called subscribers is furnished from the main exchange. During conversation the following relays are in operated position in the trunk circuit: relays 630, 660, 690, 713, 730, 740, 750, and 790. After conversation and in response to subscriber S replacing his receiver, the closed loop extending to the distant exchange is opened at the switchhook springs and series relay 713 thereupon deenergizes. At armature 714 relay 713 upon deenergizing, opens the circuit of relay 740 which deenergizes after an interval. At armature 742 relay 740 opens the circuit of relay 730 which thereupon deenergizes. At armature 732 relay 730, upon deenergizing, opens the circuit of relay 790 which likewise deenergizes and at armature 731 opens a point in the talking circuit. The automatic switches in the main exchange are released in the well-known manner and the trunk line is made available for other calls. In the case where the call extended to a manual exchange the distant main-exchange operator would get a supervisory signal to indicate when the calling subscriber has hung up.

Holding circuit

In order to describe how local subscribers equipped with a push-button, such as push-button PB, can hold a trunk call while making a local call, it will be first assumed that subscriber S is connected in a trunk call over the trunk line shown in Figs. 5, 6, and 7. The main-exchange subscriber is advised by subscriber S to wait on the line while she completes a local connection. Subscriber S now operates the push-button PB to ground conductors 101 and 102, thereby shunting the upper windings of differential relay 614 and series relay 713. This shunt circuit extends from ground at the main exchange over conductor 794, armature 731, upper winding of series relay 713, normally closed springs controlled by armature 701, conductor 616, upper winding of differential relay 614, armature 631, conductor 561, wiper 551, conductor 102, through the substation circuit to ground at the push-button PB. Series relay 713 is maintained energized over its lower winding from ground at the push-button PB by way of conductor 101, wiper 555, conductor 565, armature 636, lower winding of differential relay 614, conductor 697, normally closed springs controlled by armature 705, lower winding of series relay 713, armature 723, and over conductors 795 to battery at the main exchange. Differential relay 614, however, is unbalanced over the circuits just traced and accordingly operates its armature 615 to energize relay 700 in its first step by way of armature 704 and its resting contact. Relay 700, upon operating in its first step, operates only armature 703 to prepare a circuit for operating itself to its second step, and also completes the circuit for short circuiting its upper

winding. This short circuit extends from ground at armature 615, conductor 626, armature 704 and resting contact, upper winding of relay 700, armature 703, normally closed springs controlled by armature 712, conductor 627, armature 691, and through the resting contact of armature 643 to ground.

When subscriber S releases the push-button PB ground is removed from the conductors 101 and 102, thereby again completing the energizing circuit through the upper and lower windings of differential relay 614 to cause such relay to deenergize. At armature 615 differential relay 614, upon deenergizing, removes the short circuit from around relay 700, thereby causing relay 703 to operate to its second step. This circuit may be traced as follows: from ground at armature 643 and resting contact, armature 691, conductor 627, normally closed springs controlled by armature 712, armature 703, and through the upper and lower windings of relay 700 to battery. The remaining armatures (indicated by the Roman numerals II) now operate. At armatures 704 and 705 two-step relay 700 completes a holding bridge including resistance 706 across the talking conductors extending to the main exchange; at armature 702 completes an obvious circuit for energizing relay 680; and at armature 704 prepares a circuit for energizing slow-to-release relay 710. Relay 680, upon energizing, at armatures 681 and 685 connects the windings of line relay 610 in bridge of the line extending to subscriber S. At armature 682 relay 680 connects conductor 124 to relay 620; at armature 683 opens a point in the circuit of relay 690, which, however, at this time is maintained energized in response to the operation of relay 610; and at armature 684 grounds conductor 122.

Line relay 610 is now energized over the following circuit: from ground through the lower winding of relay 610, armature 605, armature 685, lower winding of differential relay 614, and thence over the calling loop to the line of substations S and back to the upper winding of differential relay 614 and from thence by way of armature 681 and armature 601 through the upper winding of relay 610 to battery. At armature 611 relay 610 connects marking battery through the winding of cut-off relay 600 to conductor 123 and the corresponding bank contacts in the local finders; at armature 612 completes a circuit for maintaining slow-to-release relay 690 in energized position; and at armature 613 grounds the local finder start conductor 9 to operate the start relay 420 to cause a finder of an idle local finder connector link to hunt for and find the marking potential connected to conductor 123.

Start relay 420 in the finder connector distributor is energized in the same manner as previously described and at armature 421 operates relay 400. At armature 402 relay 400 operates relay 410, completes the finder test circuit at armature 401 and completes the circuit to the finder magnet 168 at armature 403.

The finder magnet 168 and line stepping relay 230 operate as previously described to step the wipers of the finder until the marking potential on conductor 123 is found by test wiper 153. When test wiper 153 engages its twenty-first bank contact, relay 600 energizes in series with relays 220 and 230 as follows: from ground through the lower winding of relay 230, normally closed springs controlled by armature 226, lower winding of relay 220, conductor 228, wiper 412,

armature 401, wiper 413, conductor 163, wiper 153, conductor 123, armature 611, and through the winding of cut-off relay 600 to battery. At armature 221 relay 220 again completes the circuit for energizing relay 210; at armature 222 completes the circuit for energizing relay 280; at armature 223 prepares the circuit for the series relay 270; at armature 224 grounds the guard conductor 227 to cause the finder connector distributor to preselect another idle link; at armature 225 grounds conductor 123 by way of conductor 163 and wiper 153 for maintaining relay 600 energized; and at armature 226 disconnects the lower winding of relay 220 and connects the lower talking conductor to line relay 15 230. At armature 211 relay 210 completes a circuit including both talking conductors for line relay 230, which is maintained energized; at armature 212 maintains relay 220 energized; at armature 213 prepares a point in the connector test circuit; and at armature 214 prepares a point in the impulsing circuit.

Line relay 230 is now energized over both windings in series over the calling loop as follows: from ground through the lower winding of relay 230; working contact and armature 226, armature 206, conductor 165, wiper 155, conductor 125, armature 681, through the upper winding of differential relay 614, armature 631, conductor 561, wiper 551, conductor 102, through the substation loop to conductor 101, wiper 555, conductor 565, armature 636, through the lower winding of differential relay 614, armature 685, conductor 121, wiper 151, conductor 161, armatures 201 and 211, and through the upper winding of line relay 230 to battery. At armature 281 relay 280 prepares a point in the circuit used in transferring a call, and at armature 282 prepares a point in the circuit through the upper winding of local release relay 200 to automatically cause the release of the local finder connector link in case the connector is operated to originate or answer a trunk call. At armature 283 relay 280 opens a point in the locking circuit of switching relay 290 to make it release, when operated later, dependent upon the operated condition of the local release relay 200.

In the trunk circuit cut-off relay 600, upon energizing, at armatures 601 and 605 disconnects relay 610 from the talking conductors 125 and 121. At armature 602 relay 600 completes its own locking circuit to grounded conductor 123; at armature 603 connects the grounded conductor 123 through the winding of relay 690 to maintain the latter relay energized; and at armature 604 disconnects ground from finder start conductor 9. Relay 610, upon deenergizing, at armature 611 opens a point in the original energizing circuit of relay 600; at armature 612 opens a point in the original energizing circuit of relay 690; and at armature 613 opens a further point in the circuit to the finder start conductor 9.

The line of subscriber S is now connected to the local finder connector link shown in Fig. 2 and in response to the operation of the calling device CD in accordance with the telephone number of the desired local subscriber the line relay 230 is correspondingly operated over the circuit just traced. In the same manner as previously described, the connector is operated to complete the connection to the desired local subscriber.

In case subscriber S at this time should attempt to answer another trunk call or originate a trunk call while holding a trunk, then local release relay 200 is operated to automatically

release the local finder connector link to prevent such trunk call. If subscriber S attempts to answer another trunk call, local release relay 200 is energized from the marking ground at 5 armature 323 as follows: from ground by way of armature 323, when marginal relay 315 is energized as previously described, conductor 380, eighth bank contact and wiper 352, conductor 233, armature 282, armature 271, and through 10 the upper winding of local release relay 200 to battery. In case subscriber S attempts to originate a trunk call, local release relay 200 energizes from marking ground at armature 367 and marking relay 362 is energized as previously described. This circuit may be traced 15 from ground at armature 367, conductor 319, ninth bank contact and wiper 352, conductor 233, armatures 282 and 271, and through the upper winding of local release relay 200 to battery. 20 The operation of local release relay 200 at armatures 201 and 206 opens the circuit of line relay 230 to cause its deenergization and at armature 202 opens the locking circuit of switching relay 290 to cause the latter relay to deenergize. The 25 local finder connector link in this case is released in the same manner as previously described.

Assuming now that subscriber S has completed a call to another local subscriber and that subscriber S now wishes to release the local connection and return to the held trunk, in order to return to the held trunk subscriber S pushes the push-button PB, thereby unbalancing the differential relay 614 to cause its energization. Differential relay 614, upon energizing, at armature 35 615 completes the circuit by way of conductor 626 and armature 704 and its working contact for energizing slow-to-release relay 710. At armature 711 relay 710 temporarily places a bridge including resistance 617 across the talking 40 conductors 561 and 565 to reduce the click in the receiver of the substation set. At armature 712 relay 710 completes a new circuit for holding two-step relay 700 in energized position from grounded conductor 626. When the push-button 45 PB at substation S is released, differential relay 614 deenergizes and at armature 615 disconnects ground from conductor 626, thereby opening the circuit of the two-step relay 700 and slow-to-release relay 710. At armatures 701 and 705 50 two-step relay 700 disconnects the trunk-holding bridge including resistance 706 from across the trunk conductors 794 and 795 and completes the talking circuit to the line of substation S. At armature 702 relay 700 opens the circuit of relay 55 680, which thereupon deenergizes; at armature 703 opens a point in its own circuit; at armature 704 opens a further point in the circuit of relay 700; and at its resting contact prepares its original energizing circuit. At armatures 681 60 and 685 relay 680 opens the circuit to line relay 230 in the local finder connector link to cause the deenergization of this relay and the release of the local finder connector link as previously described. At armatures 683 relay 680 opens one 65 point in the circuit of relay 690 at its working contact but at its resting contact completes another circuit from grounded armature 663 for maintaining this relay in operated position. At armature 684 relay 680 disconnects ground from 70 conductor 122 to cause the deenergization of relay 280 in the local finder connector link. Slow-to-release relay 710 deenergizes after an interval and at armature 711 opens the bridge across conductors 561 and 565 to permit conversion thereover. At armature 712 relay 710 75

prepares a point in the circuit for operating two-step relay 700 in its second step. The subscriber S and the distant main-exchange subscriber are again connected over the previously traced talking circuit and after conversation may release the connection in a manner similar to that previously described.

Trunk lines in use in calls originated by the local subscriber are held while the local subscriber completes a local connection and returned to in the same manner as described for the trunk line in use on incoming calls.

Transfer circuits

In order to describe how local subscribers may transfer trunk lines from one local line to another, it will be assumed that subscriber S is connected to the trunk line shown in Figs. 6 and 7 and that subscriber S desires to transfer the call to subscriber S'. In the same manner as previously described subscriber S operates her push-button PB to cause the two-step relay 700 in the trunk to close the trunk holding bridge and to cause a finder of an idle local finder connector link to be connected to conductors 121 to 125, inclusive, of this trunk line. After receipt of dial tone subscriber S dials the number of subscriber S' to cause the connector to complete the connection to the line of subscriber S' as previously described. The talking circuit between subscriber S' and subscriber S extends through the local finder connector link and trunk circuit as follows: from line conductors 101 and 102 of line S, wipers 551 and 555 of the trunk finder, conductors 561 and 565, armatures 681 and 685, through the upper and lower windings of differential relay 614 in parallel, armatures 681 and 685, conductors 125 and 121, wipers 185 and 151, conductors 161 and 165, armatures 201 and 206, armatures 211 and 226, through the upper and lower talking condensers and the upper and lower windings of differential relay 244, armatures 261 and 263, armatures 291 and 293, wipers 351 and 356, and thence over the line conductors 301 and 302 to substation S'. 45

Subscriber S now informs subscriber S' that such subscriber is desired on a trunk connection. Subscriber S' thereupon operates his push-button PB to ground conductors 301 and 302 through the substation circuit. Relay 244 in the local finder connector link is a differential relay and has both its windings connected in series over the called substation loop as follows: from grounded conductor 264, armature 262, lower winding of combined busy and back-bridge relay 250, lower winding of differential relay 244, working contact and armature 263, armature 298, conductor 239, wipers 356, conductor 382, and thence through the substation circuit to conductor 301, wiper 351, conductor 282, armature 291, armature 261 and working contact, upper winding of differential relay 244, and through the upper winding of relay 250 to battery. Since both windings of the differential relay are equal and oppose each other, the differential relay 244 does not therefore operate.

Now, when the push-button PB at substation S' is operated to ground conductors 301 and 302, the lower winding of differential relay 244 is shunted, thereby causing the differential relay 244 to operate its armature 245. At armature 245 differential relay 244 completes a circuit for operating the two-step relay 240 in its first step as follows: from ground at armature 684, conductor 122, wiper 154, conductor 164, armature 70 75

- 245, and through the upper winding of two-step relay 240 to battery. Two-step relay 240 operates only armature 242 in its first step and at such armature connects ground to its lower winding as well as completing a short circuit including armature 245 around the lower winding. Two-step relay 240 will only energize to its second step when the two windings are energized in series.
- 10 When subscriber S' releases the push-button PB, ground is therefore removed from conductors 301 and 302 and the shunt around the lower winding of differential relay 244 is removed and the differential relay 244 accordingly deenergizes.
- 15 When differential relay 244 deenergizes, armature 245 opens the short circuit around the lower winding of relay 240, with the result that the two-step relay 240 now energizes in its second step from grounded conductor 164
- 20 through both windings in series. At armature 241 relay 240 grounds the test conductor 310 of line S' by way of conductor 234 and wiper 353; at armature 243 and resting contact disconnects ground from conductor 247 to mark this local
- 25 finder connector link as calling in the transfer distributor by disconnecting ground from the bank contact terminating this conductor; and at armature 243 and working contact relay 240 grounds the common start conductor 246 to energize start relay 430 in the transfer distributor.
- Start relay 430, upon energizing, at armature 431 prepares the circuit for short circuiting cut-through relay 440 as long as test wiper 491 engages grounded bank contacts; at armature 432
- 30 completes a circuit for energizing cut-through relay 440 as soon as test wiper 491 loses ground. Assuming that the test wiper 491 is in engagement with a grounded bank contact, then relay 440 is short circuited by way of armatures 431
- 35 and 432 and therefore does not energize. At the same time a circuit is completed for energizing the motor magnet 434 as follows: from ground encountered by the test wiper 491, armature 431, through the normally closed springs controlled
- 40 by armature 442, armature 481, interrupter springs 433, and through the winding of motor magnet 434 to battery. Motor magnet 434 energizes over the above-traced circuit, positions its pawl preparatory to stepping the wipers of the
- 45 transfer distributor, and operates interrupter springs 433 to interrupt its own circuit. Motor magnet 434 deenergizes and advances the wipers of the transfer distributor one step. At interrupter springs 433 magnet 434 again completes its energizing circuit as long as test wiper 491
- 50 engages grounded bank contacts.
- In case the wipers of the transfer distributor are not resting in engagement with the bank contacts terminating in the local finder connector link which is used in transferring the call, then the wipers are advanced step by step until test wiper 491 loses ground. With the test wiper 491 in the position shown, cut-through relay 440 is energized in response to the operation of start relay 430 over the following circuit: from ground by way of armature 432, through the winding of cut-through relay 440, normally closed springs controlled by armature 442, armature 481, interrupter springs 433, and
- 55 through the winding of motor magnet 434 to battery. Motor magnet 343 is marginal and will not energize in series with cut-through relay 440. At armature 441 relay 440 prepares a point in the time release circuit; at armature 442 closes
- 60 a holding circuit for itself independent of battery
- 65

through the winding of motor magnet 434; at armature 443 completes an energizing circuit for relay 410; and at armature 444 connects busy tone by way of wiper 495 to conductor 266 and thence to the line of substation S in the well-known manner to inform subscriber S of the transfer.

Relay 470 energizes over an obvious circuit and at armature 473 grounds conductor 264 by way of wiper 493 in order to hold relays 200, 220, 10 and 260 in the local finder connector link energized after the slow-to-release relay 210 later on deenergizes. At armature 471 relay 470 starts the weighted spring 472 to vibrating to intermittently connect ground at armature 443 to the lower winding of marking relay 480. Marking relay 480 is slow to operate and therefore does not energize until spring 472 practically ceases to vibrate. After an interval relay 480 energizes and at armature 482 grounds the transfer conductor 312 of line S' by way of wiper 492, conductor 238 and wiper 355 in order to place transfer marking potential indicating the line S' as the line selected to which the trunk finder is to transfer the call. At armature 481 relay 480 opens a further point in the circuit to motor magnet 434; at armature 483 prepares a circuit for relay 460 and the upper winding of relay 480; at armature 484 completes the circuit for energizing relay 450; at armature 485 prepares a substitute ground for ground at armature 464; at armature 486 and resting contact disconnects ground from conductor 489; and at its working contact grounds conductor 265 to complete a circuit for energizing local release relay 200 in the local link and relay 620 in the trunk line in series.

The circuit for energizing relay 450 extends from grounded armature 443, armature 461, armature 484, and through the winding of relay 450 to battery. Relay 450 operates its weighted armature 451 and completes a circuit for energizing relay 460 and for energizing the upper winding of marking relay 480. Relay 460 is energized from ground by way of armature 483, armature 441, armature 451 and working contact, through the normally closed springs controlled by armature 462, and through the winding of relay 460 to battery. A branch of this circuit extends by way of armature 451 and working contact through the upper winding of marking relay 480 for maintaining this relay in operated position. At armature 461 relay 460 opens the circuit of relay 450, which accordingly deenergizes to start the weighted armature 451 vibrating between its contacts in order to hold marking relay 480 in energized position when the circuit through its lower winding is opened at armature 463. At armature 462 relay 460 completes a locking circuit for itself from grounded armature 443 and at armature 464 substitutes ground at armature 485 for ground at the normally closed springs controlled by this armature. Weighted armature 451 vibrates for a predetermined time to maintain marking relay 480 energized for a period of time sufficient to permit the transfer of the call. In case the call, due to some trouble, is not transferred in this predetermined time, marking relay 480 deenergizes and removes the transfer condition and therefore when the trunk finder no longer is connected to a substation loop the trunk line is automatically released. Regardless of whether the call is transferred or not, relay 480 is de-

energized after the predetermined time interval by the vibrating arm 451.

Returning now to the trunk and at a time when marking relay at armature 486 grounded conductor 265, relays 200 and 620 are energized over the following circuit: from ground by way of armature 486, wiper 494, conductor 265, armature 281, lower winding of local release relay 200, conductor 162, wiper 152, conductor 124, armature 653, armature 682, and through the winding of relay 620 to battery. At armature 621 relay 620 opens a point in the trunk test circuit at its resting contact and at its working contact closes a point in the transfer test circuit extending to transfer test wiper 553. At armature 622 relay 620 prepares a point in the circuit of relay 640; at armature 623 and working contact grounds conductor 627 and at its resting contact opens the circuit of relay 660 which accordingly de-energizes. At armature 664 relay 660, upon de-energizing, opens the circuit of relay 630 which releases after an interval. At armature 632 relay 630 completes a circuit by way of armature 662 and grounded conductor 124 for energizing relay 640; at armature 634 disconnects ground from conductor 564 to remove the busy ground from test conductor 110 of line S; and at armatures 631 and 636 opens a point in the talking circuit. At armature 641 relay 640, upon energizing, closes a bridge including resistance 617 across the two talking conductors to later on reduce the click in the receiver of the line connected to the trunk line; at armature 642 completes a locking circuit for itself by way of armature 653 and grounded conductor 124 independent of armatures 632 and 622; at armature 643 prepares a circuit for later on maintaining relay 660 in energized position through its lower winding; and at armature 644 completes an obvious circuit for energizing relay 650.

At armature 651 relay 650 prepares a holding circuit for the upper winding of stepping relay 670; at armature 652 prepares a point in the test circuit; and at armature 653 opens the original energizing circuit of relay 620, but this relay is now held energized by way of grounded conductor 124, armatures 632, 622, 642, and 682. At armature 654 relay 650 completes the previously traced circuit for energizing motor magnet 568 and at armature 655 prepares a point in the bridge circuit including resistance 637. In the same manner as previously described, motor magnet 568 energizes and at springs 569 operates the stepping relay 670 through its upper winding. At armature 671 relay 670 opens the circuit to motor magnet 568 which thereupon deenergizes and steps the wipers of the trunk finder. The interaction between stepping relay 670 and motor magnet 568 continues until transfer test wiper 553 engages a grounded bank contact or the bank contact in the trunk finder grounded through the transfer distributor and connector banks as follows: from grounded armature 482, wiper 492, conductor 238, wiper 355, transfer conductor 312 individual to subscriber S' extending to the banks of the trunk finders, sixth bank contact accessible to transfer test wiper 553 and said wiper, conductor 563, working contact and armature 621, armature 652, through the upper winding of relay 660, and through the lower winding of relay 670 to battery. Test relay 660 is energized over this circuit and stepping relay 670 is maintained in energized position to prevent further stepping of motor magnet 568. At armature 661 relay 660 completes a circuit through the upper winding of

relay 670 to assist in maintaining this relay in energized position; at armature 663 prepares a circuit for maintaining relay 690 in energized position; and at armature 664 completes the circuit for reenergizing relay 630 from grounded conductor 692. At armatures 631 and 636 relay 630 prepares points in the talking circuit; at armature 632 opens the circuit of relays 620 and 640; at armature 633 prepares a circuit for the lower winding of relay 660; at armature 634 grounds the individual test conductor 310 of called line S' by way of conductor 564 and wiper 554 to maintain the line S' busy before the busy-ground from the local connector is removed; and at armature 635 completes a bridge including the resistance 637 across the upper and lower talking conductors to reduce the click in the receiver of line S'.

Relay 620 deenergizes as soon as its circuit is opened at armature 632 and at armature 623 and its working contact disconnects ground from conductor 627 to unlock the two-step relay 700 and at its resting contact completes the circuit by way of armature 633 for maintaining relay 660 in energized position through its lower winding. At armature 622 relay 620 opens a further point in the circuit of relay 640 and at armature 621 opens the circuit through the upper winding of relay 660 and the lower winding of relay 670. Two-step relay 700 deenergizes when ground is removed from conductor 627, and at armatures 701 and 705 disconnects the trunk holding bridge and completes the talking circuit. At armature 702 relay 700 opens the circuit of relay 680 which accordingly deenergizes. Relay 680, upon deenergizing, at armatures 681 and 685 opens the talking circuit extending to the local finder connector link; at armature 683 maintains relay 690 in energized position; and at armature 684 disconnects ground from trunk conductor 122 to release the two-step relay 240 and relay 280 in the local finder connector link.

Slow-to-release relay 640 deenergizes after an interval and at armature 641 opens the bridge including the resistance 617 from across the trunk conductors. At armature 642 relay 640 opens a further point in the circuit of relay 620; at armature 643 and its working contact opens one point in the circuit of relay 660 which, however, is now held by way of armatures 623 and 633; and at armature 643 and its resting contact again grounds conductor 627 to prepare the locking circuit for relay 700. At armature 644, relay 640 opens the circuit of relay 650 which thereupon deenergizes. At armatures 651 and 652 relay 650, upon deenergizing, opens the circuit of stepping relay 670 which also de-energizes; at armature 654 disconnects ground from armature 671 to prevent the operation of motor magnet 568 when relay 670 later de-energizes; and at armature 655 opens the bridge including resistance 637 from across the trunk conductors.

Returning now to the local finder connector link and at a time when local release relay 290 energizes in series with relay 620, local release relay 200, upon energizing, at armatures 201 and 203 opens the circuit to line relay 239 which thereupon deenergizes; at armature 202 opens the locking circuit of switching relay 290, which also deenergizes; at armature 203 completes a locking circuit for itself through its upper winding by way of grounded conductor 264 which is grounded at armature 212 and by the trunk distributor wiper 493; and at armature 205

opens the circuit of slow-to-release relay 210. Line relay 230, upon deenergizing, at armature 231 opens a further point in the circuit of relay 210 and also prepares a circuit for grounding conductor 215. At armatures 291 and 298 switching relay 290, upon deenergizing, opens the circuit extending to the line of substation S', thereby opening the circuit of differential relay 244' and the combined back-bridge and busy relay 250, causing relay 250 to deenergize. At armature 293 relay 290 opens a point in its own locking circuit; at armature 294 disconnects one of the ground connections maintaining line S' busy; and at armature 296 prepares a point in the self-restoring circuit for the connector switch. Slow-to-release relay 210 deenergizes after an interval and at armature 211 opens a further point in the talking circuit in the local finder connector link. At armature 212 relay 210 disconnects one of the grounds from conductor 264, but since this conductor is grounded by the transfer distributor, relays 200, 220 and 260 are maintained energized; at armature 213 prepares a circuit of grounding conductor 216; and at armature 214 opens a point in the impulsing circuit.

When ground is disconnected from conductor 122 at armature 684 by the deenergization of relay 680, two-step relay 240 and relay 280 de-30 energize. At armature 281 relay 280 opens a point in the initial energizing circuit of local release relay 200. Two-step relay 240, upon deenergizing, at armature 241 disconnects ground from conductor 234 to disconnect one of the 35 busying grounds from conductor 310, which however, at this time is grounded by way of armature 634 and trunk wiper 554; at armature 242 opens a point in its own locking circuit; at armature 243 and working contact opens the 40 circuit to the transfer distributor start relay 430 which now deenergizes in case another call is not waiting to be transferred; and at armature 243 and its resting contact grounds conductor 247. In case another call is waiting to be transferred, 45 then start relay 430 is maintained energized and the ground on conductor 247 short circuits relay 440 as follows: from grounded conductor 247, wiper 491, armature 431, winding of relay 440 to ground at armature 432. In case no other call is waiting to be transferred, then relay 430, upon deenergizing, at armature 432 opens the circuit of relay 440. In either case 50 relay 440 deenergizes and at armature 441 opens the circuit by way of vibrating arm 451 to the 55 upper winding of marking relay 480 to cause the deenergization of this relay. At armature 442 relay 440 opens a point in its own locking circuit and at armature 443 opens the circuits of relays 460 and 470. Relay 470, upon de-60 energizing, at armature 473 disconnects ground from conductor 264 to cause the release of relays 200, 220 and 260 in the local finder connector link. Relay 460 deenergizes and restores the circuit controlled thereby to normal. Marking relay 480, upon deenergizing, at armature 481 prepares a circuit to motor magnet 434 to 65 allow the transfer distributor to find another local finder connector link in case another call is to be transferred. At armature 482 relay 480 70 disconnects ground from conductor 238 to remove the transfer marking potential and at armature 486 grounds conductor 489 and disconnects ground from conductor 265. The transfer distributor is now restored to normal and 75 may be again used to transfer the next call.

When the transfer distributor disconnects ground from conductor 264, relays 200, 220 and 260 in the local finder connector link deenergize. At armature 225 relay 220 disconnects ground from conductor 123 to deenergize the 5 cut-off relay 600 in the trunk circuit and at armature 224 and resting contact completes the self-interrupting circuit for causing the wipers of the connector to be restored to their normal positions. When the connector wipers reach 10 their normal position the local finder connector link may be used on other calls.

Returning to the trunk line at the time relay 220 of the local finder connector link opened the circuit of relay 600, said relay thereupon re-15 stores and places the trunk line in the same condition as it was before a local subscriber held the trunk line in order to transfer such call to another local subscriber. At this time relays 630, 660, 690, 713, 730, 740, 750, and 790 are in 20 operated position. The trunk is now connected to the line of substation S' and the talking circuit may be traced as follows: from the heavy talking conductors in the trunk extending from the distant exchange, wipers 551 and 555 in 25 engagement with their sixth bank contact, conductors 302 and 301 extending over cable No. 6 to Fig. 3 and thence to the substation S'. If desired, subscriber S' may transfer the call to another local subscriber in the same manner as 30 just described.

Trunk connections may be transferred as many times as desired between local subscribers' lines.

Restricted service

35

Some subscribers are restricted from originating or answering trunk calls, and such subscribers' lines have negative battery potential connected through a resistance to its individual 40 bank contact accessible to wiper 152. For example, as shown in Fig. 1, line No. 09 has battery through resistance Z connected to the sixteenth bank contact accessible to wiper 152. Therefore, if subscriber 09 should attempt to answer 45 or originate a trunk call by dialing digit "8" or digit "9", then local release relay 200 is energized to cause the release of the local finder connector link. In attempting to answer a trunk call, relay 200 is energized over the following 50 circuit when relays 314 and 315 energize as previously described: from ground by way of armature 323, conductor 380, eighth bank contact and wiper 352, conductor 233, armatures 282 and 292, through the lower winding of local 55 release relay 200, conductor 162, wiper 152, conductor 29, through the resistance Z to battery.

In attempting to originate a trunk call, relay 200 is energized over the following circuit when relay 362 is energized as previously described: 60 from ground by way of armature 361, conductor 379, ninth bank contact and wiper 352, and from thence over the previously traced circuit through the lower winding of local release relay to battery through the resistance Z. The energization of relay 200 causes the release of this local finder connector link as previously described, and, when ground is disconnected from the subscriber's individual line and cut-off relay at armature 225 by the deenergization of relay 70 220, the individual line and cut-off relay deenergizes and then again energizes in its first step to cause another local finder connector link to find this line and connect dial tone thereto. While restricted subscribers cannot 75

answer or originate trunk calls, such subscribers can be connected to trunk lines in response to the non-restricted subscribers transferring trunk calls thereto. The transfer of such calls takes place in the same manner as previously described.

Attendant's cabinet

The attendant's cabinet shown in Fig. 5 is in reality one of the local subscribers' lines equipped with special facilities for answering incoming trunk calls when traffic is of such a nature that it is desirable to have one party answer all incoming trunk calls and then transfer such trunk calls to the parties desired. As will be seen, whenever the information key is depressed, the attendant's substation is connected to the local equipment over talking conductors 1 and 2 the same as any other local non-restricted subscriber's line. The transfer key, instead of a push-button PB, is provided to enable the attendant to control the operation of the differential relays in the trunk circuits and local finder connector links both to transfer and receive transferred trunk calls over the line conductors 1 and 2. In the same manner as previously described, local subscribers desiring to call the attendant dial the digits "0" and "1" to cause a local connector to connect with and signal the attendant by operating the bell RB in Fig. 5. The attendant operates the information key and removes the handset from the cradle, thereby completing the local connection. In a manner similar to that described for local subscribers the attendant, by operating the information key and the calling device CD, can complete connections over conductors 1 and 2 and the local finder connector link to desired local subscribers' lines. In addition, the attendant can hold any subscriber's local connection by operating the hold key, thereby bridging conductors 1 and 2 to hold the local connection, after which the attendant may restore the information key and answer any incoming trunk calls. Since these local connections over conductors 1 and 2 are established in the same manner as described for the other local subscribers' lines, it is therefore thought unnecessary at this time to describe the detailed operation other than set forth above.

Assuming now that the attendant is to answer all incoming trunk calls, then signal key SK is operated and locked in its working position. Under these conditions relay 507 is disconnected so as to prevent the operation of the common trunk signals and relay 516 is connected in place thereof. Now, when any trunk is seized on an incoming call the alternating current signalling relay, such as relay 760, is operated to connect battery through a resistance to the common signalling conductor 609 to energize relay 516. Assuming that the trunk shown in Figs. 6 and 7 is the trunk in use, then relay 760 is energized as previously described and at armature 761 completes the circuit for energizing relay 516 as follows: from ground through the winding of relay 516, working contact of signal key SK, conductor 609, resting contact and armature 662, conductor 624, armature 761, and through resistance 763 to battery. At armature 517 relay 516 completes a circuit for operating the buzzer B in order to inform the attendant that there is an incoming trunk call on one of the trunks.

75 While only one two-way release and trunk

answer key and its associated relays 500 to 540, inclusive, are shown, it will be understood that this attendant's cabinet is provided with a second key and a second set of similar relays and that such second set is connected to the trunk finder 5 over conductors similar to conductors 544 to 548, inclusive, to the twenty-second bank contacts accessible to the wipers of the trunk finder. This second set is provided to enable the attendant to handle more than one trunk call at the same 10 time. In response to the operation of the buzzer B, the attendant will operate either one of the trunk answer keys and remove the handset HS from the cradle. Assuming that the attendant operates the trunk answer key shown, then 15 springs 525 and 526 connect the talking conductors of the attendant's substation circuit to conductors 544 and 548 by way of resting contact and springs 522 and 523 of the information key. A circuit for energizing marking relay 510 20 may now be traced from ground through the right-hand operated cradle springs MS, operated trunk answer springs 528, normally closed springs controlled by armature 503, and through the winding of marking relay 510 to battery. 25 At armature 511 relay 510 prepares a point for connecting marking potential or ground to conductor 545 to cause the trunk finder to connect with the attendant's substation circuit; at armature 512 closes a shunt around springs 524; at 30 armature 513 prepares a circuit for relay 530; at armature 514 prepares a point in a holding bridge for the trunk; and at armature 515 grounds conductor 371 to complete an energizing circuit for relays 315 and 316. 35

Relay 314 is energized over grounded conductor 370 in the same manner as previously described when relay 770 in the trunk circuit operated its armature 772. The circuit for energizing relays 315 and 316 may now be traced as follows: from ground at armature 505, armature 515, conductor 371, armature 320 and working contact, through the winding of marginal marking relay 315, and through the windings of relay 316 to battery. Relays 315 and 316 operate as before and relay 315 at armature 321 grounds conductor 372, thereby marking the twenty-first bank contact accessible to wiper 552 by way of armatures 511 and 502 and conductor 545. In response to the operation of relays 315 40 and 316 the trunk distributor is operated to find the calling trunk and to ground conductor 629 as previously described to cause the energization of relay 650. 45

At armature 654 relay 650 completes the circuit for energizing finder motor magnet 568, which in turn causes the energization of stepping relay 670. The interaction between motor magnet 568 and relay 670 causes the wipers of the trunk finder to be advanced step by step until the trunk test wiper 552 finds the marking ground. When test wiper 552 engages the marked contact, relay 660 is energized and relay 670 is maintained energized as follows: from ground by way of armature 321, conductor 372, armatures 511 and 502, conductor 545, wiper 552, conductor 562, resting contact and armature 621, armature 652, upper winding of relay 660, and through the lower winding of stepping relay 670 55 to battery. Relay 670 at armature 671 maintains the circuit to motor magnet 568 open to prevent further operation of the trunk finder wipers and relay 660 at armatures 663 and 664 causes the energization of relays 690 and 630 60 as previously described. At armatures 631 and 65 664 causes the energization of relays 690 and 630 as previously described. At armatures 631 and 70 75

636 relay 630 connects the attendant's substation circuit in bridge of the trunk and at armature 635 completes a local bridge including resistance 637 to cause the disconnection of ring-
 5 current to take place at the main exchange. At armature 633 relay 630 opens the circuit to relay 770 which deenergizes to open the circuit of relay 314 and at armature 634 grounds conductor 564 for energizing relay 500 as follows:
 10 from ground at armature 634, conductor 564, wiper 554, conductor 547, and through the winding of relay 500 to battery. At armature 501 relay 500 completes a circuit by way of armature 521 for lighting the supervisory lamp SL;
 15 at armature 502 opens a point in the marking circuit; at armature 503 substitutes ground on conductor 547 for ground at cradle springs MS, for holding marking relay 510 energized through the release key; at armature 504 prepares a point for transmitting busy tone as well as preparing a holding circuit for the trunk and at armature 505 disconnects ground from conductor 371 to deenergize relays 315 and 316 in the trunk distributor to cause the distributor to
 20 operate as previously described to disconnect ground from conductor 629, thereby causing the deenergization of relay 650. At armatures 651 and 652 relay 650 opens the circuit of relay 670 which now deenergizes; at armature 654 opens a point in the circuit to motor magnet 568; and at armature 555 opens the bridge across conductors 561 and 565.

The attendant's substation circuit is now connected in a talking circuit to the trunk conductors 794 and 795 as follows: talking conductors 794 and 795 extending to the main exchange, armatures 731 and 723, through the upper and lower talking condensers connected in bridge of the upper and lower windings of series relay 40 713, normally closed springs controlled by armatures 701 and 705, conductors 616 and 697, through the upper and lower windings of differential relay 614, armatures 631 and 636, conductors 561 and 565, wipers 551 and 555, conductors 544 and 548, working contact and springs 525 and 526 of trunk answer key, resting contact and springs 522 and 523 of the information key, and from thence over the attendant's substation telephone circuits. Series relay 713 is energized 45 in series with the substation circuit from battery and ground at the main exchange and said relay at armature 714 completes the circuit for energizing relay 740. Relay 740 energizes and performs the same functions as previously described.
 50 The talking battery for this connection is furnished from the main exchange.

If the attendant wishes to answer a second incoming trunk call before he has disposed of the first one, he will merely restore the trunk answer key previously operated to normal, which places a holding bridge across the main exchange trunk. This holding bridge may be traced as follows: from conductor 548, through the normally closed springs controlled by spring 525 when restored, armature 514, resistance 506, armature 504, through the normally closed springs controlled by spring 526 to conductor 544. The attendant now operates the other trunk answer key (not shown) which causes the 55 trunk finder associated with the trunk line having the second incoming call to connect such trunk line to the attendant's substation circuit through the second trunk answer key in the same manner as described for the first call. In this 60 last instance the finder wipers are connected to

their twenty-second bank contacts instead of their twenty-first bank contacts to complete the circuit through the second trunk answer key to the attendant's substation circuit. If the attendant should answer two main-exchange trunk calls in this manner, he may hold or transfer either call at will, as the restoration of either trunk answer key holds the connected trunk. It will now be assumed that the attendant, after talking to the main-exchange subscriber over the first trunk connection, desires to transfer the call to substation S. In order to transfer this call the transfer key is momentarily operated, which places a holding bridge across the trunk and causes a local finder to find this particular 10 trunk. When the attendant hears dial tone transmitted from the local connector, he will dial the local station number and ask the party there to take over the trunk call. The local subscriber then presses the push-button to cause 15 the trunk call to be transferred to his own station. The attendant receives the busy signal and thereupon restores the trunk answering key and replaces the handset HS on the cradle.

In response to the operation of the transfer 20 key a circuit is completed for operating two-step relay 530 in its first step as follows: from ground by way of springs 535 of the transfer key, springs 527 of the trunk answer key, armature 533 and resting contact, and through the lower 25 winding of two-step relay 530 to battery. Transfer key springs 536 connect direct ground to the upper talking conductor of the trunk, thereby shunting the upper winding of differential relay 614 in the trunk to cause its 30 energization. The circuit for shunting the upper winding of differential relay 614 may be traced as follows: from ground at transfer key springs 536, information key springs 523 and its working contact, trunk answer key spring 526 and working contact, conductor 544, wiper 551, conductor 561, armature 631, upper winding of differential relay 614, conductor 616, normally closed springs controlled by armature 701, through the upper winding of series relay 713, armature 731 and 35 over trunk conductor 794 to ground at the main exchange. Differential relay 614 is now unbalanced and therefore energizes and completes the circuit for energizing two-step relay 700 as previously described. Series relay 713 is maintained 40 energized over its lower winding. Relay 530, upon energizing in its first step, closes only its armature 531 and 532 and at armature 531 prepares a circuit through its upper winding to operate two-step relay 530 to its second step when the transfer key is restored, and at armature 532 prepares a circuit for energizing two-step relay 540 to its 45 second step. Two-step relay 700 energizes and operates only its armature 703 in its first step to connect grounded conductor 627 by way of normally closed springs controlled by armature 712 to the upper winding of two-step relay 700.

When the transfer key is restored, spring 535 removes one of the grounds short circuiting the upper winding of relay 530, with the result that 50 two-step relay 530 now energizes in its second step over the following circuit: from grounded armature 513, by way of armatures 541 and 531, and through the upper and lower windings of relay 530 in series to battery. Two-step relay 70 530 now operates its armature 533 to prepare a circuit for two-step relay 540 and at armature 534 connects busy tone to trunk answer springs by way of armatures 504 and 514. When the transfer key is restored, transfer springs 536 dis- 55

connect ground from the upper trunk talking conductor, with the result that the shunting circuit around the upper winding of differential relay 614 is opened and differential relay 614 now deenergizes. In response to the deenergization of differential relay 614, said relay at armature 615 removes the short circuit from around the upper winding of relay 100, with the result that two-step relay 100 now energizes to its second step over the following circuit: from ground at armature 643 and resting contact, armature 691, conductor 627, normally closed springs controlled by armature 712, armature 703, and through the upper and lower windings in series to battery. At armature 701 and 702 two-step relay completes a bridge across the trunk and at armature 704 prepares a circuit for relay 710. At armature 702 relay 700 completes a circuit for energizing relay 680. At armatures 681 and 685 relay 680 connects the attendant's substation loop across the windings of line relay 610 to cause the latter relay to energize; at armature 682 prepares a circuit for connecting relay 620 to conductor 124; and at armature 684 grounds conductor 122 to mark this trunk as calling in the local finder banks.

The operation from here on is identical with that previously described for transferring trunk calls. The only difference is that the attendant's substation circuit instead of a local subscriber's station such as S is connected to the trunk conductors 561 and 565. The operation of relay 610 causes a local finder connector link to hunt for and find the trunk in use and when such local finder connector link finds the trunk marked over conductor 122 the attendant receives dial tone in a manner similar to that previously described in transferring calls. As the transfer of this trunk call is substantially the same as previously described, only a brief description will therefore be given. After receipt of dial tone, the attendant operates her calling device CD in accordance with the digits of line S, or digits "0" and "8", to cause the local connector to connect with line S. The line circuit for controlling the line relay of the local finder connector link may be traced as follows: from the line conductors of the attendant's telephone circuit, through the resting contact at information key springs 522 and 523, through the operated springs 525 and 526 of trunk answer key to conductors 544 and 548, wipers 551 and 555, conductors 561 and 565, armatures 631 and 636, through the upper and lower windings of differential relay 614, armatures 681 and 685, conductors 125 and 121, wipers 151 and 155, conductors 161 and 165, armatures 201 and 206, armatures 211 and 226, and through the upper and lower windings of line relay 230 to battery and ground.

After subscriber S answers, the talking circuit between the attendant and the line of substation S may be traced as follows: over the heavy line conductors from the attendant's telephone circuit to line relay 230 where the heavy talking conductor extends by way of the upper and lower talking condensers, through the upper and lower windings of differential relay 244, armatures 261 and 263, armatures 291 and 298, conductors 232 and 239, wipers 351 and 356, conductors 101 and 102 extending over the cable No. 08, and to the substation circuit at line S.

The attendant now requests subscriber S to accept the trunk call, which the subscriber does by operating her push-button PB. The operation

of the push-button PB causes the differential relay 244 in the local link to operate as previously described. The operation of relay 244 causes the two-step relay 240 to operate in its first step and then in its second step when differential relay 244 deenergizes in response to the restoration of the push-button. At armature 241 relay 240 maintains the line of subscriber S busy by connecting ground to test conductor 110 by way of conductor 234 and wiper 353 and at 10 armature 243 causes the operation of the transfer distributor as previously described.

When marking relay 480 in the transfer distributor operates, said relay at armature 482 marks the line S with transfer or marking potential in the transfer bank of the trunk finder as follows: from ground by way of armature 482, wiper 492, conductor 238, wiper 355, conductor 112 extending by way of cable No. 08, to the fifteenth bank contact accessible to transfer 20 wiper 553. At armature 485 relay 480 grounds conductor 264 to hold relays 200, 220, and 260 in energized position, and at armature 486 grounds conductor 265 to energize relay 620 in the trunk circuit over the following circuit: from ground 25 by way of armature 486 and working contact, wiper 494, conductor 265, armature 281, through the lower winding of local release relay 200, conductor 162, wiper 152, conductor 124, armature 653, armature 682, and through the winding of 30 relay 620 to battery. Relays 200 and 620 energize over this circuit and relay 200 accomplishes the same functions as previously described.

At armature 621 relay 620 opens the trunk test circuit and prepares the transfer test circuit; at armature 622 prepares a circuit for relay 640; and at armature 623 opens the circuit of relay 660, which now deenergizes. At armature 664, relay 660 opens the circuit of relay 630 which deenergizes after an interval. At armature 632 relay 630 completes the previously traced circuit for energizing relay 640; at armature 631 and 636 opens points in the talking circuit; and at armature 634 opens the circuit to relay 500 which now deenergizes. 45

Before relay 630 deenergizes, switching relay 290 in the local finder connector link deenergizes in response to the energization of relay 200 to connect busy tone by way of armature 297 and armature 253 to the attendant's substation 50 circuit over the heavy talking conductors. When the attendant hears the busy tone, he is apprised of the fact that the called local subscriber has accepted the trunk call and that the call is being transferred thereto. 55

Relay 640, upon energizing, at armature 644 completes the circuit for energizing relay 650. At armature 654 relay 650 operates the motor magnet 568 to cause the trunk finder and stepping relay 670 to operate as previously described 60 until the transfer test wiper 553 finds the marked transfer potential extending from the transfer distributor through the connector and transfer distributor banks. When the test wiper 553 finds the marked transfer potential, relay 6560 is energized and relay 670 maintained energized over the following circuit: from ground at armature 482 and thence over the previously traced circuit to conductor 112 terminating in the fifteenth bank contact accessible to wiper 553, and thence by way of wiper 553, conductor 563, working contact and armature 621, armature 652, through the upper winding of relay 660 and the lower winding of relay 670 to battery. At armature 664 relay 660 reenergizes 75

relay 630. At armature 632 relay 630 opens the circuit to relays 620 and 640 and at armature 634 connects ground to test conductor 110 by way of conductor 564 and wiper 554 to maintain line S busy. At armature 623 relay 620 opens the locking circuit of two-step relay 700 which now deenergizes. At armatures 701 and 705 two-step relay 700 opens the trunk holding bridge and restores a point in the talking circuit and at armature 702 opens the circuit of relay 680 which now deenergizes. At armatures 681 and 685 relay 680 opens the talking circuit extending to the local link and at armature 684 opens the circuit to relays 240 and 280 in the local finder connector link.

Slow-to-release relay 640 deenergizes after an interval to open the bridge across the trunk conductors at armature 641 and at armature 644 opens the circuit of relay 650. At armatures 651 and 652 relay 650, upon deenergizing, opens the circuit of relay 670 which deenergizes and at armature 655 opens the bridge across the trunk conductors 561 and 565.

The local finder connector link and the transfer distributor return to normal position as previously described and when relay 220 in the local link deenergizes relay 600 in the trunk circuit also deenergizes. The trunk is now connected to the line of subscriber S over the wipers of the trunk finder by way of conductors 101 and 102.

In the attendant's cabinet relay 500 deenergizes when its circuit is opened by the deenergization of relay 630, and at armature 501 opens the circuit to the supervisory lamp SL. At armature 502 relay 500 prepares a point in the trunk test circuit for subsequent use; at armature 504 opens a point in the trunk holding bridge; at armature 505 grounds conductor 371; and at armature 503 restores the circuit for relay 510 through the normally closed springs before relay 510 deenergizes when ground is disconnected from conductor 547, so that relay 510 is now held energized from ground extending from the right-hand cradle springs by way of trunk answer springs 528.

When the attendant hears the busy tone indicating the transfer of the call, the attendant restores the trunk answer key and replaces the handset on the cradle. In response to the restoration of the trunk answer key the attendant's substation circuit is disconnected from conductors 544 and 548 and at springs 528 the circuit of relay 510 is opened. At armature 511 relay 510, upon deenergizing, opens a point in the trunk marking circuit; at armature 512 opens the shunt around springs 524; at armature 513 opens the circuit of relay 530 which now deenergizes; at armature 514 opens a further point in the trunk holding bridge; and at armature 515 disconnects ground from conductor 371.

The supervisory lamp SL is lit as soon as a trunk call has been extended to the attendant's cabinet and remains lit either until the attendant has transferred the call or until the calling party has hung up and the attendant has released the trunk by momentarily throwing the trunk answer key to its release position to operate the release key. The attendant cannot clear out the supervisory signal SL by replacing her handset; hence the supervisory lamp makes it impossible for the attendant to overlook the extension or completion of any incoming trunk call.

It will be remembered that relay 500 is maintained energized over conductor 547 as long as

the calling main-exchange subscriber or operator does not release regardless of the operations performed by the attendant and therefore relay 500 maintains the supervisory lamp SL lit. For example, it will be assumed that the attendant attempts to release a trunk call by replacing the handset on its cradle and by restoring the trunk answer key, thereby operating the release key. The operation of the release key opens the circuit of relay 510 which deenergizes and at armature 514 opens the trunk holding bridge to cause the deenergization of series relay 713. At armature 714 relay 713 opens the circuit of relay 740 which deenergizes after an interval. At armature 744 relay 740 again connects relay 780 in bridge of trunk conductors 794 and 795, whereupon the latter relay energizes and at armature 781 maintains relay 750 energized. At armature 751 relay 750 maintains relay 790 energized, while the latter relay at armature 792 maintains relay 630 energized. Since relay 630 is maintained energized, said relay at armature 634 maintains relay 500 energized over the following circuit: ground by way of armature 634, conductor 564, wiper 554, conductor 547, and through the winding of relay 500 to battery. When the main-exchange subscriber or operator releases, then relay 780 deenergizes to open the circuit of relay 750. At armature 752 relay 750, upon deenergizing, opens the circuit of relay 730 which now deenergizes. At armature 732 relay 730 opens the circuit of relay 790. At armature 791 relay 790, upon deenergizing, marks the trunk line as idle in the trunk distributor and at armature 792 opens the circuit to relay 630. Relay 630 now deenergizes and restores the remaining relays to their normal positions as previously described, and at armature 634 opens the circuit of relay 500 which now deenergizes to extinguish the supervisory lamp SL.

Considering now the case in which the attendant has answered an incoming trunk call and then called a local busy subscriber in an attempt to transfer the trunk call thereto, when the local connector encounters the busy line busy tone is transmitted to the attendant, thereby informing the attendant that the local desired line is busy. In order to be reconnected to the trunk line the attendant momentarily reoperates the transfer key and at springs 535 completes the circuit for energizing relay 540 as follows: From ground by way of transfer springs 535, trunk answer key springs 527, armature 533 and its working contact, and through the lower winding of two-step relay 540 to battery. Relay 540 operates in its first step and closes only armature 542 in order to short circuit its upper winding as well as prepare a circuit for operating itself to its second step. When the transfer key is restored, the short circuit around the upper winding of relay 540 is removed and relay 540 operates to its second step over the following circuit: from ground at armature 532, armature 542, and through the upper and lower windings in series to battery. At armature 541 relay 540 opens the circuit of relay 530 which now deenergizes. At armature 532 relay 530 opens the circuit of relay 540 which also deenergizes. When transfer key is first operated, springs 536 complete the circuit for unbalancing the differential relay 614 as previously described to cause its energization. At armature 615 relay 614 operates relay 710 by way of armature 704 and its working contact. At armature 711 relay 710, upon energizing, closes a bridge across the talking conductors in-

cluding the resistance 617 and at armature 712 maintains the circuit of two-step relay 700 from ground at armature 615 extending by way of conductor 626 and armature 104. Now, when the transfer key is restored, differential relay 614 deenergizes and at armature 615 opens the circuits of relays 700 and 710. At armatures 701 and 705 two-step relay 700, upon deenergizing opens the trunk holding bridge including the resistance 706 and reconnects the talking conductors. At armature 702 relay 700 opens the circuit of relay 680, which thereupon deenergizes. At armatures 681 and 685, relay 680 opens the circuit to the line relay in the local finder connector link to cause the release of the local finder connector link. The calling main-exchange subscriber and the attendant are now reconnected over the heavy talking conductors as previously traced. The attendant now informs the main-exchange subscriber that the desired party is busy, whereupon the calling subscriber and attendant cause the release of the trunk as previously described.

Considering now the case in which the attendant has answered an incoming trunk call and has called a local subscriber to transfer the call thereto, while the attendant is waiting for the called subscriber to answer, such attendant may answer a second incoming trunk call by first restoring the first trunk answer key and then operating the second trunk answer key. In the same manner as just described the restoration of the first trunk answer key closes a holding bridge for the first local connector as follows: from the upper and lower windings of line relay 230, over the heavy talking conductors previously traced including the talking conductors 121 and 125 and talking conductors 544 and 548 to the trunk answer key which is now restored and from thence through the normally closed springs controlled by springs 525 and 526 to the holding bridge including armature 504, resistance 506, and armature 514. Now, when the called local subscriber responds, such subscriber will hear the busy tone transmitted from the attendant's cabinet over the following circuit: from busy tone conductor 360, the busy tone condenser, armature 534, to armatures 514 and 504, through the normally closed springs controlled by springs 525 and 526, conductors 544 and 548, wipers 551 and 555, conductors 561 and 565, armatures 631 and 636, through the upper and lower windings of differential relay 614, armatures 681 and 685, conductors 125 and 121, wipers 151 and 155, conductors 161 and 165, and from thence over the heavy talking conductors of the local finder connector link to the called line. The called subscriber, upon hearing busy tone after being called, knows that the attendant has called. The called subscriber may wait for the attendant to come back on the line or may operate her push button to accept the trunk call without waiting for the attendant. In case the subscriber does not wait for the attendant, then when relay 630 in the trunk is deenergized during the transfer as previously described to open the circuit of relay 500, such relay therefore deenergizes and opens the circuit of the supervisory lamp SL at armature 501. When the lamp SL is extinguished the attendant knows that the trunk call has been transferred and he need not return thereto.

The operator at the main exchange can flash the supervisory lamp SL to resign the attendant by connecting ringing current to the trunk

conductors 794 and 795 to reoperate the alternating current signalling relay 760. The repeated operation of relay 760 in response to the intermittent application of ringing current at the main exchange intermittently operates relay 520 over the following circuit: from ground at armature 486 and resting contact, conductor 489, through the winding of relay 520, conductor 546, wiper 553, conductor 563, working contact and armature 662, conductor 624, armature 761, and through the resistance 763 to battery. Since relay 500 is energized at this time, the intermittent operation of relay 520 at armature 521 causes the lamp SL to be flashed from ground at armature 501.

Considering now the case in which the attendant has answered two incoming trunk calls by the operation of her two trunk answer keys and that a third trunk call arrives, in this case the attendant may operate her information key and dial the digit "8" to answer this trunk call the same as any other local non-restricted subscriber.

The attendant may also originate an outgoing trunk call by operating her information key and dialling the digit "9" to cause an idle trunk to be connected to her substation circuit by way of the information key in the same manner as described for a local subscriber. If the attendant wishes to transfer any trunk call made or answered over the information trunk, she may do so like any other local subscriber by momentarily operating the transfer key which takes the place of the push-button on the local subscriber's line. From the foregoing it will be seen that the attendant is in a position to answer and hold three trunk calls, if necessary, two by means of the trunk answer keys and the third over the information trunk. If a local subscriber wishes to transfer a trunk call to the attendant, such local subscriber dials the number of the information trunk, or digits "0" and "1", after having pressed the push-button. In the same manner as a local subscriber the attendant answers by operating the information key and accepts the trunk call over the information trunk by momentarily operating the transfer key.

Having described the invention, what is considered new and is desired to have protected by Letters Patent is pointed out in the following claims:

What is claimed is:

1. In a telephone system, a local exchange and a distant exchange, a plurality of subscribers' lines in said local exchange, a plurality of trunk lines connecting said exchanges, incoming trunk signals common to all said trunk lines, means for operating all said signals responsive to an incoming trunk call on any one of said trunk lines, only two conductors individual to each subscriber's line for connecting each line to the local exchange, and means for automatically connecting the trunk line in use in the incoming trunk call with any subscriber's line in response to such subscriber exercising a predetermined control over its two individual conductors.

2. In a telephone system, a local exchange and a distant exchange, a plurality of subscribers' lines in the local exchange, a plurality of trunk lines connecting said exchanges, incoming trunk signals common to all said trunk lines, means for operating all said signals responsive to an incoming call on any one of said trunk lines, means for connecting the trunk line in use in

- the incoming trunk call with a subscriber's line in response to such subscriber answering the trunk call, individual signalling means for each local subscriber's line, and means for directly 5 operating only the connected subscriber's individual signalling means after such subscriber has hung up in response to application of ringing current to said trunk line at the distant exchange.
10. 3. In a telephone system, subscribers' lines, a connector switch having access to said lines, a plurality of trunk lines, a trunk answering position in said switch, means controlled by a calling subscriber for operating said switch to said 15 trunk answering position in case such subscriber desires to answer an incoming trunk call on any one of said trunk lines, and means automatically responsive to the connection of said switch to said trunk answering position for automatically 20 connecting the trunk line in use in the incoming call to the said calling subscriber's line and for thereafter restoring said connector switch for common use by other subscribers.
4. In a telephone system, subscribers' lines, a 25 connector switch having access to said lines, a plurality of trunk lines, a trunk answering position and a trunk calling position in said switch, means controlled by a calling subscriber for operating said connector switch to connect with 30 said trunk answering position or to said trunk calling position dependent upon whether the subscriber desires to answer an incoming trunk call on any one of said trunk lines or desires to originate an outgoing trunk call over an idle one 35 of said trunk calls, means automatically responsive to the connection of said switch to said trunk answering position for automatically connecting the trunk line in use in an incoming call to the calling subscriber's line or automatically 40 responsive to the connection of said switch to said trunk calling position for automatically connecting an idle one of said trunk lines to said calling subscriber's line, and means automatically 45 responsive to the connection of said trunk line to the calling subscriber's line for restoring said connector switch for common use by other subscribers.
5. In a telephone system, a local exchange and a main exchange, two-way trunk lines connecting 50 said exchanges, a selecting means in said local exchange terminating each said trunk line, local subscribers' lines accessible to said selecting means, local apparatus common to said local subscribers' lines, two conductors extending from each local subscriber's line to said local apparatus, means in said local apparatus controlled by a local subscriber over such subscriber's two individual conductors for marking such subscriber's line in said selecting means and 55 for initiating the operation of a first idle one of said selecting means in response to originating an outgoing trunk call and in response to answering an incoming trunk call for initiating the operation of the selecting means in use on 60 said incoming call, and means in said selecting means for hunting for and finding the marked subscriber's line.
6. In a telephone system, a local exchange and a main exchange, two-way trunk lines connecting 65 said exchanges, local subscribers' lines accessible to each other and to said trunk lines, means for establishing connections between said trunk lines and said subscribers' lines, holding circuits in said trunk lines, means in each trunk line for completing its individual holding cir- 70
- cuit, subscriber controlled means for operating said last means to complete the holding circuit in an established trunk connection while thereafter completing a local connection, and means for guarding said held trunk connection from 75 intrusion.
7. In a telephone system, a local exchange and a distant exchange, two way trunk lines connecting said exchanges, a plurality of local subscribers' lines, each local subscriber's line 10 comprising a substation circuit and only two conductors connecting the substation circuit to the local exchange, said subscribers' lines accessible to each other and to said trunk lines, means for establishing connections between said 15 trunk lines and said subscribers' lines over the two conductors individual to such subscribers' lines, an individual holding circuit in each trunk line, means in each trunk line for completing its individual holding circuit, subscriber controlled means for operating said last means over the subscriber's two individual conductors to 20 complete the individual holding circuit in an established trunk connection while thereafter completing a local connection over said two individual conductors, and means for guarding said held trunk connection from intrusion.
8. In a telephone system, subscribers' lines, only two conductors individual to each subscriber's line, trunk lines, connecting means associated with said trunk lines, means controlled over the two conductors of a subscriber's line for operating one of said connecting means to connect one of said trunk lines with said subscriber's line, means controlled over said two 30 conductors and said connecting means for connecting the said subscriber's line to another subscriber's line, and means controlled over the two conductors of said other subscriber's line for reactuating said connecting means to disconnect 35 said trunk line from the first subscriber's line and connect it to said other subscriber's line.
9. In a telephone system, subscribers' lines, only two conductors individual to each subscriber's line, trunk lines, connecting means associated with said trunk lines, means controlled over the two conductors of a subscriber's line for operating one of said connecting means to connect one of said trunk lines with said subscriber's line, means controlled over said two 40 conductors and said connecting means for connecting the said subscriber's line to another subscriber's line, means controlled over the two conductors of said other subscriber's line for reactuating said connecting means to disconnect 45 said trunk line from the first subscriber's line and connect it to said other subscriber's line.
10. In a telephone system, subscribers' lines, trunk lines, means for connecting one of said trunk lines with one of said subscriber's lines, a hold circuit in each trunk line, means for splitting said connected trunk line in two sections and for completing the individual hold circuit across one of the sections, and means for thereafter completing a local connection between 50 said subscriber's line and another subscriber's line over the other section of said trunk line.
11. In a telephone system, subscribers' lines, trunk lines, means for connecting one of said trunk lines with one of said subscriber's lines, a hold circuit in each trunk line, means for 55

splitting said connected trunk line in two sections and for completing the individual hold circuit across one of the sections, means for thereafter completing a local connection between 5 said subscriber's line and another subscriber's line over the other section of said trunk line, and means for releasing said local connection and for reestablishing said first trunk connection.

12. In a telephone system, subscribers' lines, 10 trunk lines, means for connecting one of said trunk lines with one of said subscriber's lines, a hold circuit in each trunk line, means for splitting said connected trunk line in two sections and for completing the individual hold circuit 15 across one of the sections, means for thereafter completing a local connection between said subscriber's line and another subscriber's line over the other section of said trunk line, and means controlled by said other subscriber for disconnecting said first subscriber's line from said 20 trunk line, for connecting said other subscriber's line with said trunk line, for removing the holding circuit and reconnecting said sections, and for thereafter releasing said local connection.

13. In a telephone system, subscribers' lines, 25 trunk lines, means for connecting one of said trunk lines with one of said subscriber's lines, a hold circuit in each trunk line, means for splitting said connected trunk line in two sections 30 and for completing the individual hold circuit across one of the sections, means for thereafter completing a local connection between said subscriber's line and another subscriber's line over the other section of said trunk line, and means 35 for guarding said trunk line from intrusion during such connections.

14. In a telephone system, a local exchange, 40 local subscribers' lines terminating in said exchange, connecting apparatus common to said subscribers' lines for interconnecting said lines, a main exchange, trunk lines interconnecting said exchanges accessible to said subscribers' lines, means for connecting one of said trunk lines to one of said subscribers' lines, means in 45 said trunk line controlled over the two talking conductors of said subscriber's line and the two talking conductors of said trunk line for splitting said trunk line into a main exchange section and a local exchange section, a holding circuit in said trunk line completed across said main exchange section in response thereto, and means also responsive thereto for connecting said local exchange section of said trunk line with one of said common connecting apparatus to 50 connect said subscriber's line thereto.

15. In a telephone system wherein a plurality 55 of subscribers' lines are each provided with a push-button, a plurality of trunk lines connected with a distant exchange, means for connecting an answering subscriber's line to a trunk line in use on an incoming call, holding means in said trunk line operated in response to the operation of the answering subscriber's push-button for holding said trunk call while such answering subscriber completes a local connection with a second local subscriber's line, and means thereafter responsive to the operation of the second subscriber's push-button for transferring the held trunk call from the said answering subscriber's line to the said second subscriber's line.

16. In a telephone system, a local exchange, 60 a plurality of subscribers' lines at said local exchange, a distant exchange, a plurality of trunk lines connecting said exchanges, holding means 65 in each trunk line, a push-button individual to

each subscriber's line, each of said push-buttons being common to all said trunk lines, and means operated responsive to the operation of a subscriber's push-button when any one of said trunk lines is connected thereto for operating the individual trunk holding means. 5

17. In a telephone system, a local exchange, 10 a plurality of local subscribers' lines at the local exchange, a distant exchange, a plurality of trunk lines connecting said exchanges, holding 15 means in each trunk line, a push button individual to each local subscriber's line, each said push-button being common to all said trunk lines, means operated responsive to the operation of a local subscriber's push button in case such subscriber's line is the first subscriber connected to a trunk line for operating the individual trunk holding means, and means operated responsive to the operation of a second local subscriber's push-button in case such subscriber's line is 20 connected with a first local subscriber's line by way of a trunk line for disconnecting said first local subscriber's line from the trunk line and for transferring the trunk connections to the second subscriber's line. 25

18. In a telephone system, a local exchange, 30 a plurality of local subscribers' lines at the local exchange, a distant exchange, a plurality of trunk lines connecting said exchanges, means for connecting a local subscriber's line with one of 35 said trunk lines, means for connecting said local subscriber's line with a second local subscriber's line through a portion of said trunk line, a push-button individual to each local subscriber's line, and means operated in response to the operation 40 of either subscriber's push-button for connecting said trunk line exclusively to the subscriber's line corresponding to the operated push-button.

19. In a telephone system wherein a trunk 45 finder terminating a trunk line is operated to complete incoming, outgoing and transfer calls for local subscribers' lines, two test wipers and a single test circuit in said finder, the first of said wipers normally connected to said test circuit and effective for completing incoming and 50 outgoing trunk calls responsive to the operation of said finder, and means for disconnecting said first wiper from said test circuit and for connecting said second test wiper to said test circuit to complete transfer calls responsive to the operation 55 of said finder.

20. In a telephone system, a local exchange and a distant exchange, a plurality of local subscribers' lines in the local exchange, a plurality of trunk lines connecting said exchanges, 60 a trunk finder individual to each trunk line, and means for automatically operating the trunk finder of a trunk line in use on an incoming call or the trunk finder of an idle one of said trunk lines in response to the local subscriber's 65 dialling two different predetermined digits, one for incoming trunk calls and the other for outgoing trunk calls.

21. In a telephone system, a local exchange, 70 local subscribers' lines at said local exchange, a distant exchange, trunk lines interconnecting said exchanges, a trunk distributor, means including circuits for normally operating said trunk distributor to preselect an idle one of said trunk lines for use in outgoing trunk calls, and means responsive to an incoming call on one of said trunks and a local subscriber answering said trunk call for altering said circuits to operate said trunk distributor to select the trunk line in use in the incoming calls. 75

22. In a telephone system, a local exchange, local subscribers' lines at said local exchange, a distant exchange, trunk lines interconnecting said exchanges, a trunk distributor, means including circuits for normally operating said trunk distributor to preselect an idle one of said trunk lines for use in outgoing trunk calls, means responsive to an incoming call on one of said trunks and a local subscriber answering said 5
 10 trunk call for altering said circuits to operate said trunk distributor to select the trunk line in use in the incoming call, and means responsive to said trunk distributor selecting said trunk line in use in the incoming trunk call for connecting said trunk line to the subscriber's line answering such trunk call.
23. In a telephone system, a local exchange and a distant exchange, a plurality of local subscribers' lines in said local exchange, a plurality of trunk lines connecting said exchanges, incoming trunk signals common to all said trunk lines and common to said subscriber's lines, an attendant's line in said local exchange, a single trunk signal individual to said attendant's line 20 and common to said trunk lines, and attendant controlled means for rendering either said incoming trunk signals or said single signal operative in response to an incoming trunk call on any one of said trunk lines.
24. In a telephone system, a local exchange and a distant exchange, an attendant's line in said local exchange, a plurality of trunk lines interconnecting said exchanges, a first and a second trunk answer key associated with said 25
 30 attendant's line, a trunk signal common to said trunk lines and associated with said attendant's line, means responsive to an incoming trunk call on any one of said trunk lines for operating said signal, and means for automatically connecting the trunk line in use in said incoming call with said attendant's line in response to the operation of either one of said trunk answer keys.
25. In a telephone system, a local exchange and a distant exchange, an attendant's line in said local exchange, a plurality of trunk lines interconnecting said exchanges, a first and a second trunk answer key associated with said attendant's line, a trunk signal common to said trunk lines and associated with said attendant's 35
 40 line, means responsive to an incoming trunk call on any one of said trunk lines for operating said signal, and means for automatically connecting the trunk line in use in said incoming call with said attendant's line in response to the operation of either one of said trunk answer keys.
26. In a telephone system, a local exchange and a distant exchange, an attendant's line in said local exchange, a plurality of trunk lines interconnecting said exchanges, a first and a second trunk answer key associated with said attendant's line, a trunk signal common to said trunk lines and associated with said attendant's 45
 50 line, means responsive to an incoming trunk call on any one of said trunk lines for operating said signal, and means for automatically connecting the trunk line in use in said incoming call with said attendant's line in response to the operation of either one of said trunk answer keys.
27. In a telephone system, a local exchange and a distant exchange, a plurality of trunk lines connecting said exchanges, an attendant's line and a local subscriber's line in the local exchange, means for connecting a trunk line in use in an incoming call with said attendant's 55
 60 line, means controlled by the attendant for dividing said trunk line in two sections and for completing a holding bridge across one of said sections, means for connecting said attendant's line with said local subscriber's line by way of the other section of said trunk line, and means for transmitting a distinctive signal to the local subscriber's line from said attendant's line over said last connection.

JOHN H. VOSS. 50
